[57] **ABSTRACT**

Wideband service between any two stations in a key telephone system is provided by a multilink matrix switching network. A register circuit common to all of the stations and common to all of the links monitors the status of each link and allows access to the matrix network from calling stations only when at least one link of the network is idle. On dial selective connections, signals identifying the calling station are communicated to the register circuit directly from each calling station. Signals identifying the called station are communicated to the register via the link assigned by the register to serve a given call request. On direct signaling connections, the identification signals of the called station are communicated to the register circuit from the called station in response to signals from a calling station. The system is arranged such that when a conference is desired the added stations are connected by the register circuit to the link serving the original calling and called stations so that the entire wideband conference is contained on the same link.

MULTILINK WIDEBAND INTERCOMMUNICATION SYSTEM

Background of the Invention

This invention relates generally to key telephone systems and more particularly to an arrangement for providing wideband intercommunication service between the key stations.

DESCRIPTION OF THE PRIOR ART

Extensive development of key telephone systems in recent years has made possible the provision of numerous special features which render such key telephone systems more convenient and flexible. For example, circuit arrangements have been provided which enable communication paths to be established from any station to any one of a number of lines by operating a key associated with the desired line. In such systems, it is customary to arrange one of the lines as an intercom line, thereby allowing a subscriber at any key station to communicate with a subscriber at any other key station merely upon the operation of the intercom key at each of the stations.

In such arrangements, the intercom line is usually arranged such that the enabling of the intercom key at any station enables separate transmission paths to be established from the transmitter and receiver of the associated station to respective transmit and receive buses of a common intercom link. An amplifier, commonly called a talk-back amplifier, is connected between the buses such that transmission from any station to any other station is possible via the single link intercom. Under such an arrangement, transmission originating from any station will be received at all the connected stations including the originating station. When more than two stations access the link during the same time interval, transmission is established between all the stations on the link on a conference basis.

Recent developments in wideband service, an example of which is PICTUREPHONE video service, have made it possible to further enhance the versatility of key telephone systems. Unique problems are presented in such systems when the wideband service is extended to the intercom line. For example, in a key telephone system arranged for PICTUREPHONE video service, it is possible for two or more video stations to access the common link at the same time, each station transmitting separate images. Since reconstruction of the received data at the terminating station is dependent upon the proper reception of synchronizing (SYNC) signals from the transmitting station, and since these signals will be out of phase with each other when transmitted from different stations, a picture resulting from simultaneous transmission from two or more stations will be visually unintelligible.

A further problem arises in that the conventional audio-only common link intercom techniques wherein the transmit pairs and the receive pairs of the connected stations are bridged by a talk-back amplifier are not feasible for wideband transmission since the echo suppression equipment necessary under such an arrangement would be extremely sophisticated and uneconomical.

In copending application of Bush-Olson-Saltus, Ser. No. 5,243, filed Jan. 23, 1970, now U.S. Pat. No. 3,649,761 there is disclosed a single link intercom ar-

rangement for overcoming these problems while providing wideband transmission between selected stations of a key telephone system. The Bush et al disclosure teaches a wideband intercom capable of serving up to ten stations. In larger key systems more than one link must be provided in order to adequately serve the increased traffic demand. Under these conditions where more than one link is provided problems arise in that all stations must have access to all links and every station must be connectable to every other station such that the video output leads of one station are connected to the video input leads of the connected station.

In situations where additional stations are to be added to an existing video intercom connection, the added stations must be connected to the same link as is the existing connection. In addition, the added stations must be connected in a manner that will not interfere with the video transmission.

An important feature of existing key telephone systems is the provision for establishing conference connections between a first key station, a line such as a PBX line connected to that station and any other key station. In wideband telephone installations, it is desired to provide similar three-party connections. Under such a system, provision must be made to insure that at any one time only two of the stations are interconnected for wideband transmission while all three parties remain connected throughout the call for audio transmission.

In the situation where the three-party conference involves a first key station connected in video fashion to a second key station over one of the intercom links and also connected for video transmission to a line it is often desirable to transfer the connection such that the first station is removed from the connection so that the second station and the line have direct video capability therebetween.

Therefore, it is an object of this invention to provide a key telephone system wherein wideband communication may be established between any of the stations on a multilink intercom basis without transmission interference between the stations.

It is another object of this invention to provide a key telephone system having a multilink intercom wherein a wideband connection may be established between a line and a called station and the connection may be extended in conference fashion between the line, the called station, and a station connected to the called station over a selected one of the intercom links, and wherein the called station may be removed so that an exclusive wideband connection may be established from the line to the connected station via the selected intercom link.

SUMMARY OF THE INVENTION

These and other objects are obtained in accordance with one exemplary embodiment of the invention wherein a key telephone system is arranged to provide each key station with access to a wideband multilink intercom while at the same time assuring that wideband connections are enabled between only two stations at any one time.

In the embodiment a key telephone system is arranged to provide wideband service on a multilink intercom basis by using a register circuit common to all

of the links and common to all of the stations. Access to the links from each station is via the register circuit which circuit is arranged to monitor the busy-idle status of each link and to serve a calling station only when at least one of the links is idle. Called stations are connected to a calling station via a matrix network controlled jointly by the selected idle link and the register circuit. The matrix network contains three distinct buses, one each for audio, video, and control purposes. The video bus is further divided into a receive bus and a transmit bus. The calling station is connected to the matrix network such that the video output leads from that station's transmitter are connected to the video receive bus and the video input leads from that station's receiver are connected to the transmit bus. The calling station, under control of its own logic circuits, is connected to the matrix network in the above reversed manner while the wideband quad leads from the called station are connected to the network in a nonreversed manner such that bidirectional wideband transmission may occur between the stations.

The register circuit responds to uniquely coded signals supplied by a calling station for connecting that station to the matrix network while the called station is connected to the matrix network under selective control of the calling station. When an additional station is to be added to the connection the added station may be connected to the matrix network under direct control of the calling station. In this situation the added station is forced by the calling station to supply its code to the register.

Additional stations may also be added to the matrix by recalling the register to the calling station and dial selecting the station to be added. The register circuit is arranged in such a manner that an added station is always added to the proper link.

The system is arranged for three-party video conferencing on an add-on basis between a first station, a line connected to the first station and a second station connected to the first station via any of the intercom links. On such a conference, all the parties are connected together for continuous audio transmission. However, the direction of the wideband transmission is under exclusive control of the first station and is either between that station and the line or between that station and the second station over the selected intercom link. This feature is provided by a control circuit which bridges the audio bus of the selected link to audio transmission leads of the line. The wideband transmission between the parties is controlled from the first station and an add-on transfer circuit is arranged such that when a three-party conference has been established any station may be removed and an exclusive wideband connection is switched to continue between the remaining station and the line.

In accordance with one feature of the invention a multilink intercom is arranged among a number of key stations in such a manner that exclusive audio and wideband transmission is possible concurrently between pairs of stations served by the intercom.

In accordance with another feature of the invention, a wideband multilink intercom is arranged with control circuitry for matching the transmit and receive wideband lead pairs of a called station with the proper wideband lead pairs of a calling station on a selected link

while insuring that only the called and the calling stations have wideband access to that link at any one time.

In accordance with still another feature of the invention, a wideband key telephone system having a multilink wideband intercom is arranged for three-party wideband conferencing on an add-on basis between a first station, a line connected to the first station and a second station connected to the first station via the intercom link and further arranged such that the first station may become removed from the connection.

DESCRIPTION OF THE DRAWING

The foregoing objects, features and advantages, as well as others of the invention, will be more apparent from the following description of the drawing, in which:

FIG. 1 is essentially a block diagram showing the interrelation of the exemplary embodiment of the invention;

FIGS. 2 through 30 are schematic drawings showing in greater detail the interrelation of the components of the exemplary embodiment; and

FIG. 31 shows the manner in which the other figures should be arranged.

It will be noted that FIG. 2 through 30 employ a type of notation referred to as "detached contact" in which an X shown intersecting a conductor represents a normally open contact of a relay and a bar shown intersecting a conductor at right angles represents a normally closed contact of a relay; "normally" referring to the unoperated condition of the relay. The principles of this type of notation are described in an article entitled "An Improved Detached Contact Type Schematic Circuit Drawing" by F. T. Meyer in the September 1955 publication of the *American Institute of the Electrical Engineers Transactions, Communications and Electronics*, Vol. 74, pages 505-513.

It will be noted also that in order to simplify the disclosure and thus facilitate a more complete understanding of the embodiment, the relays, relay contacts and other electromechanical devices shown in FIG. 2 through 30 have been given systematic designations. Thus, the number preceding the letters of each device correspond to the figure in which the control circuit of the device is shown. Thus, the coil of relay 5A0 is shown in FIG. 5. Each relay contact, either make, break or transfer, is shown with its specific contact number preceded by the designation of the relay to which it belongs. For example, the notation 5A0-1 indicates contact number 1 of relay 5A0 the coil of which is shown in FIG. 5.

INTRODUCTION

The present invention is illustrated in a key telephone system wherein any key station may be selectively connected to any one of a number of switching network lines in response to the enabling of a key associated with that line. For purposes of illustration, it is intended that audio-only connections and the audio portion of wideband connections are completed to the key stations from Private Branch Exchange (PBX) or Central Office (CO) lines in a manner well known in the art. One such arrangement is disclosed in the H. T. Carter U.S. Pat. No. 2,850,579, issued Sept. 2, 1958. It will be assumed that the high frequency or data portion of a wideband connection is completed over a wide-

band link.

band quad which consists of a transmit pair of wires and a receive pair of wires. An example of a key telephone system arranged to provide wideband service between any line and any key station is disclosed in copending application of S. E. Bush, P. E. Crouse, and G. E. Saltus, Ser. No. 875,261, filed Nov. 10, 1969. It will be assumed further that the selector circuit of the present embodiment is of a type commonly used in intercom systems with selective ringing controlled by the calling station. One such selective intercommunication arrangement is disclosed in the C. E. Morse U.S. Pat. No. 3,450,845, issued June 17, 1969.

In order to further facilitate an understanding of the invention, the description of the operation of the exemplary embodiment has been subdivided into a general description portion designated 1.0 and a detailed description portion designated 2.0. Section 1.0 and its subsections describe the invention in general terms with respect to FIG. 1. Section 2.0 and its subsections described the invention in detail with respect to FIG. 2 through 30.

1.0 GENERAL DESCRIPTION

Referring now to FIG. 1, the present invention is illustrated in an audio-video key telephone system having any number of key stations, such as stations (1st) 301 and (27th) 201. The wideband units 401 and 202, which in the embodiment are PICTUREPHONE video display sets, are each individually associated with certain ones of the stations.

In the embodiment, each station is arranged with five communication lines (L1-L5); with four of the lines (L1-L4) extended to a conventional key telephone system through line circuits associated with each line, and the remaining line (L5), the intercom line, extending to a matrix network 2301, 2302, 2401 under control of register circuit 1901 and link circuits 2501, 2801, and 2802.

1.1 System Block Functions — Station Circuit

The station circuits, such as station circuits 1401, 1402, and 1501, serve to interface the respective station sets with the switching portions of the system. When a station goes off-hook, the associated station circuit signals the register circuit 1901 and transfers thereto, via special coding leads, the identity of the calling station. The station circuit, in conjunction with the register circuit, provides potential to illuminate either the white lamp at the station set on audio calls or the red lamp on wideband calls. When a station circuit is connected to a link circuit, it serves to hold the switch matrix crosspoint relay associated with the assigned link so as to eliminate the necessity for the register circuit to remain attached to a calling or called station. The station circuit is arranged to differentiate between being associated with a calling and a called station.

1.2 System Block Functions — Matrix Network

The matrix network 2301, 2302, and 2401 contains an array of contacts for connecting each station circuit to each link. The station circuits are connected to the horizontal multiples of the network while the respective vertical multiples form the interconnecting buses.

Each link consists of a matrix array of contacts, which array is controlled by three separate relay coils. The respective contacts of the relays generally are associated with the switching functions necessary for the audio, video, and features portion of a given call. The busy or idle status of any station is determined by testing the audio relay coil of all three links associated with that station for a holding potential thereon.

1.3 System Block Functions — Link Circuits

Each link through the matrix network is controlled by a separate link circuit 2501, 2801 or 2802. Stations are connected through the matrix to the link circuit for the purpose of dialing and for the control of functions associated with many of the optional features. Each link circuit provides talking battery in a single-ended feed to the tip and ring leads of the station connected thereto. Audible tones, such as dial tone, ringback tone, station-busy tone, and permanent signal tone are supplied by each link circuit via the battery feed connection. Control of the audible tones is initiated by the register and is then maintained individually by each link circuit until retired by a connecting station or for a nominal period of thirty seconds. The link circuits are each held in the busy state as long as at least one station maintains its tip and ring connection thereto.

1.4 System Block Functions — Register

The functions performed by the register circuit 1901 may be best described at this point by enumerating those functions in the order that they occur during the processing of a normal call. This order is as follows:

1. Recognizing a request for service by detecting a ground level on one or more of the coding leads from a signaling station circuit,
2. causing the activation of a selector therein so that the selector may respond to the station code transmitted on the coding leads,
3. selecting an idle link and enabling the seizure of that link,
4. performing a test to determine the busy or idle status of the calling party,
5. operating the calling party's cross-point matrix,
6. releasing the selector and subsequently causing the selector to be reconnected to the selected link circuit, permitting the called party's dialed number to be recognized by the selector,
7. causing dial tone to be transmitted to the calling party from the assigned link,
8. causing dial tone to be removed by the assigned link when the first dialed pulse or TOUCH-TONE digit is received by the selector,
9. performing a busy-idle test on the called party's matrix in all three links,
10. signaling the assigned link to connect the proper audible tone to the calling party's line, and
11. releasing from the assigned link by allowing the link to go into the busy state from the enabled state.

1.5 Establishment of a Connection From a Calling Station

Through the Matrix Network

When it is desired to establish an intercom connection from a station, the pickup key associated with the intercom line at that station is enabled. In addition, on PICTUREPHONE service calls the pound (#) key on a TOUCH-TONE 12-key dialer is enabled prior to the dialing of the digits associated with the called station as an indication that wideband service is required. The register circuit 1901 at this time has already determined if any one of the three intercom link circuits 2501, 2801, and 2802 is idle. The register circuit in response to the enabled intercom key thereupon seizes the detected idle link for subsequent use of the calling station. Subsequently, a path through the matrix network 2301, 2302, and 2401 is established, via the seized link, from the register to the calling station. Interposed in this path is the station circuit associated with the calling station which circuit also served to identify the calling station to the register.

The calling party, upon connection to the register, thereupon dials or key pulses the digits associated with the desired called station. The register then interrogates the matrix network associated with the called station to determine its busy-idle status. Upon a determined idle condition, the register connects the called station to the matrix network on the same link as the calling station. The register then becomes disconnected from that link and is free to handle other intercom connections from other stations on remaining idle links.

1.6 Direct Station Selection (DSS)

After a two-party call has been established either party may add an additional station. However, if the original parties are in the wideband mode the additional parties are added in an audio-only fashion. A special (DSS) key is required at each station for each specific station that a user wishes to signal directly. The operation of the DSS key takes the place of dialing and connects the calling station directly to the called station through the previously established link connection. Operation of the DSS key forces the link circuit to which that station is connected to become reenabled thereby connecting that station to the register. Lockout is provided to disallow direct station selection if the register is serving another link at that time. When the register has been successfully reconnected to the now signaling link circuit the depressed direct station signaling (DSS) key provides a signal to the called party's station circuit. That signal causes the coding leads of the called station to become active thereby causing the register circuit to respond as if the call had been initiated from the called station as opposed to its initiation from the station at which the DSS key has been operated. The register responds to the incoming code in the same manner as previously discussed for the establishment of a connection and accordingly connects the called station to the link associated with the calling station. Provision is made so that several parties may be called by successive operation of individual DSS keys at a calling station, and for permitting audible signals to be transmitted so that the calling party may determine the status of each of the direct station signaled parties.

1.7 Register Recall

After a call has been established on a given link either party may depress a register recall key thereby causing the involved link circuit to be reenabled and reconnected to the register. In this situation the enabled register recall key causes a new request for service to appear at the register without an accompanying station code on the coding leads. In this situation dial tone is returned from the link circuit to the stations connected thereto. The previously attached stations may now key pulse the code associated with the second called station and the connection will be established in the manner more fully detailed hereinafter.

1.8 Add-On Transfer Connection

In situations where it is desired to add a PBX or central office line to the intercom connection, each such added line must be capable of being connected to any one of the three system links. Add-on transfer control and connecting circuits, such as circuits **701**, **702**, and **703**, and **501**, **601**, and **602** are used to control such three-party conferences. Under this arrangement bidirectional wideband transmission is either between a first station and a PBX line or between a first station and one of the intercom links dependent only upon which of the respective pickup keys is enabled at the first station. The audio connection between the conference parties is arranged such that full three-way transmission is possible among all of the connected parties to the conference without regard to which of the pickup keys is enabled at the first station.

When one of the intercom parties goes on-hook the three-party conference previously established is automatically switched to a two-party intercom conference regardless of which of the parties to the intercom link established the original connection.

1.9 Distinctive Signaling

In order for a subscriber at a key station to distinguish between audio-only connections and video connections, two distinct signaling systems are utilized. On audio-only calls the visual signals are provided by a white line lamp and the audible signals are generated by a bell ringer. On video calls the visual signals are provided by a red line lamp and the audible signals are generated by a tone ringer.

1.10 Voice Switched Conferencing

The multilink intercom of the embodiment has been shown in conjunction with a video conference control circuit 801, 901, 902, and 1001 and a voice operated switch 1101, 1102, and 1201. These elements are detailed in FIG. 8-13 and are included in the drawing for reference purposes only. The features provided by these circuits are optional to the operation of the embodiment and may be removed therefrom in a straightforward manner without in any way interfering with the operation of the multilink intercom as described herein. The circuitry shown in FIG. 8-13 is the subject of a copending application of R. D. Reese, Ser. No. 169,329, filed Aug. 5, 1971.

2.0 Detailed Description

The following text will describe the embodiment of the invention in detail with reference to FIG. 2 through

30. Cursory examination of these figures will reveal that certain relay contacts and relay designations have been enclosed in parentheses.

The parenthetical symbol has been employed to facilitate a clear understanding of the invention by indicating that the apparatus which is enclosed therein is shown more fully in prior art telephone systems. Relay designations and contact designations which are unique to the instant embodiment are not enclosed in parentheses and are shown in complete detail.

We shall assume as hereinbefore set forth that the stations are all arranged for PICTUREPHONE wideband service. We shall further assume that each of these stations is arranged with five pickup keys with the first four such keys at each station associated with four line circuits, such as line circuit 302, FIG. 3, and the fifth key at each station associated with the multilink intercom. However, as will be more apparent from that which is contained hereinafter, any number of stations, each connectable to any number of wideband or audio-only lines, may be connected into the intercom system. Also, it should be noted that a station which is not equipped for wideband service may also access the multilink intercom for audio-only communication with any other station regardless of whether the connected station is equipped for wideband service or for audio-only service.

Since the multilink wideband intercom is arranged to function with existing key telephone systems and key telephone station equipment, existing control and signaling arrangements have been utilized throughout. For example, connections over any line, including the intercom line, are enabled by the operation of the pickup key associated with that line at each station. The enabling of the pickup key provides a signal on the associated A lead which signal is utilized in the manner to be more fully detailed hereinafter to establish and control the connection.

2.1 Calling Station Bidding for an Idle Link

Turning now to FIG. 3, assume that 1st station 301 desires to establish an intercom connection to 27th station 201 (FIG. 2), not detailed, but identical to detailed station 301. Accordingly, the pickup key at the calling station 301 associated with the intercom line, which in the embodiment is pickup key 3PU5, is enabled. Upon removing the handset from the switchhook, ground is extended through enabled switchhook contact 3SW1-1, released hold break contact 3HLD1-1 and enabled make pickup key contact 3PU5-3 and over lead A5-1 and cable 411 to 1st station circuit 1501, FIG. 15.

Ground is extended via lead A5-1 to FIG. 16 and through forward-biased diodes 16CR7 and 16CR40 and resistor 16R2 to turn on transistor 16Q4. When transistor 16Q4 turns on, transistor 16Q3 turns on momentarily by the transient voltage via capacitor 16C1. The resulting momentary ground on lead RT is unimportant at this time. Transistor 16Q4 turning on causes battery to be extended over an obvious path to FIG. 17 and through released break contact 17A-5 to one side of the 17A relay winding. The other side of the 17A relay winding is connected through diode 17CR3 and lead OP and cable 1701 to register circuit 1901, FIG. 19.

Continuing in FIG. 19 and 20, and assuming that register circuit 1901 is idle and that at least one of the links is available for establishing a connection thereon, transistor 20Q3, FIG. 20, is on thereby providing a ground from the emitter thereof through released break contact 21SYB-4, FIG. 19, to lead OP, cable 1701. The ground on lead OP is extended to FIG. 17 thereby enabling relay 17A in the calling station circuit 1501. Relay 17A remains operated due to current flowing through forward-biased diode 17CR2.

The enabling of relay 17A causes ground from lead CHI to be extended through enabled make contact 17A-3 and released break contact 17B-3 to maintain relay 17A operated without regard to the potential on lead OP from the seized register circuit. Leads CHI and CHO in conjunction with the transfer contacts 17B-3 and 17A-3 in each of the station circuits form a chain from ground on lead CHI in the 1st station circuit such that only one 17A relay in only one of the station circuits remains held in this manner. Accordingly, simultaneous seizures of the register circuit from more than one station circuit are prevented and preferential seizure treatment is given to the lowest numbered station circuit.

Continuing in FIG. 16, when the calling station seizes an available register in the manner just described and the 17A relay in the associated station circuit has operated the line lamp at the station turns on. This is accomplished from negative potential and released break contact 17P-4, enabled make contact 17A-6 and lead LH, cable 1601, to FIG. 18 and the associated hold circuit which in this case is 1st hold circuit 1803. The negative potential on lead LH is extended through the hold circuit via released break contact 18H-2 and over lead L5-1 and cable 411 to the calling station 301, FIG. 4. As shown in FIG. 4, the negative potential is extended from lead L5-1 through forward-biased diode 4N1-5 to illuminate the intercom line (line L5) white lamp WH-5.

In the event of a failure to seize a register circuit because the links are all busy, the red intercom line lamp R-5 at the calling station turns on instead of the white lamp WH-5. This is accomplished by supplying positive potential over lead L5-1 which potential biases diode 4P1-5 in the forward direction while biasing diode 4N1-5 in the reverse direction, thereby extinguishing white lamp WH-5 and illuminating red lamp R-5. On such busy conditions of the links the positive potential is present on lead L5-1 over the path just described from the associated station circuit, FIG. 16.

The circuitry which accomplishes this function is in the register circuit, FIG. 19, 20, 21, and 22. As shown in FIG. 21, when the register circuit is unavailable because all of the links are busy the 21SYB relay therein is operated via transistor 21Q12 which transistor turns on whenever ground is absent on lead SYBC. Thus, as shown on FIG. 19, the ground on lead OP is removed via enabled break contact 21SYB-4 and the 17A relay, which operated from this ground, remains normal in the calling station circuit. Also, since the 21SYB relay is operated when all of the links are busy, tone source 1903, which tone source is arranged in any one of the well-known circuit configurations operable to provide an audible tone on a line, provides tone via enabled make contact 21SYB-3 and the lead SBT of cable 1701 to the station circuit 1501, FIG. 15.

Continuing now in FIG. 15, this tone is extended through the station circuit via lead SBT and released break contact 17A-1 and over lead T (of cable pair RT5-1) and cable 411 to the calling station 301, FIG. 3 and through the enabled pickup key to the receiver (shown as part of network and dial 303) thereof. Accordingly, the subscriber is given audible as well as visual indication that a connection to the intercom link cannot be accomplished at this time because of the busy condition of all of the links.

2.2 Link Selection

In the preceding section, it was assumed that the register circuit was idle and that a link circuit was available. The following description details the exact circuitry arranged to control the register in busy as well as idle situations.

Turning now to the register circuit 1501, FIG. 21, the outputs of a binary counter, such as binary counter 2102, are logic levels appearing on leads LK10, LK11, LK20, and LK21. The counter is driven by a 120-Hz pulse shaper, such as pulse shaper 2103, which pulse shaper may be arranged in any one of the well-known circuit configurations operable to supply pulses so long as an input lead remains open. The input leads to pulse shaper 2103 are the leads respectively designated IHL1, IHL2, and IHL3. Thus, so long as these leads remain free of negative potential, binary counter 2102 continues to sequence and the output leads thereof reflect, in binary form, the status of the counters at any point in time. Thus, during one pulse leads LK11 and LK20 will have grounds thereon while at the next pulse leads LK10 and LK21 may have grounds thereon while at a third pulse leads LK21 and LK11 may have grounds thereon, this sequence being repeated at the next pulse so that again leads LK11 and LK20 will have grounds thereon. Thus, at each pulse only one pair of LK-leads of the three cables 2111, 2112, and 2113 will have grounds thereon. Each of the cable pairs just mentioned is extended to one of the three link circuits to control that circuit.

Turning now to the 1st link circuit 2501, FIG. 27, the leads LK11 and LK20 from cable 2111 are extended to transistor 27Q6 via the respective diodes 27CR11, and 27CR12, released break contact 26LB-6 and forward-biased diode 27CR13. When and only when both of the leads LK11 and LK20 are grounded, transistor 27Q6 turns on. Since both of these input leads have ground thereon from the binary counter in FIG. 21, the corresponding leads in the 2d and 3d link circuits 2801 and 2802 have at least one negative potential on their respective LK-leads thereby maintaining the 27Q6 transistors (not shown) in each of the other link circuits off. Accordingly, when transistor 27Q6 in the 1st link circuit 2501, FIG. 27, turns on negative potential is coupled to output lead IHL1 of cable 2111 which negative potential is extended to the register circuit, FIG. 21, thereby stopping pulse shaper 2103 so as to maintain the binary counter 2102 in the counting state associated with the 1st link. Thus at this point the 1st link circuit is waiting to serve the next calling station. Only when a link circuit is in this waiting or available mode will a connection be made involving that link.

Continuing in FIG. 27, when transistor 27Q6 in the 1st link circuit 2501 turns on battery is supplied to one side of the 27EL relay winding. The other side of the

27EL relay winding is connected via diode 27CR6 to transistor 27Q7 which transistor is off at this time. The winding is also connected via diode 27CR8 to lead SR which lead extends back via cable 2710 to the register circuit 1901, FIG. 21, to ground through the parallel combination of make contacts 19SR-4 and 20RB-5. Thus, the 27EL relay in the selected link circuit is inoperative until either the 19SR relay or the 20RB relay in the register circuit 1901 becomes enabled.

10 Turning now to FIG. 21, in the manner to be more fully detailed hereinafter, when the register circuit is seized by a calling station circuit the 19SR relay operates thereby providing a ground on lead SR which ground is extended to all of the link circuits. Since the 27Q6 transistor is on in the 1st link circuit the associated 27EL relay operates. The operation of relay 27EL causes the operation of relay 26EL1 which relay operates as shown in FIG. 26 from ground via enabled make contact 27EL-6.

15 The operation of relays 26EL1 and 27EL places the link circuit in the enabled condition and the link circuit will remain in this mode as long as the register is attached thereto. This link circuit is in the enabled condition only during the period during which a call is being processed and while in this mode certain input leads are cut through to the register.

20 In the manner to be more fully detailed hereinafter, when the call processes beyond the establishment stage 30 the 27EL and 26EL1 relays become released thereby transferring the link circuit from the enabled condition to the busy condition which condition is controlled by the status of the 26LB relay.

25 Continuing in FIG. 26, it will be noted that relay 26LB operates from ground via enabled make contact 27EL-6 and forward-biased diode 26CR15. The 26LB relay has an auxiliary operate path from FIG. 25 via diode 25CR14 and the enabled condition of transistor 25Q7 which transistor as will be seen from that which is contained hereinafter is maintained in its on condition from loop current flowing through resistor 25R5. Resistor 25R5 is a battery-feed resistor to a connected station and thus as long as any station is connected to the link circuit current will flow through resistor 25R5 and maintain transistor 25Q7 on thereby maintaining relay 26LB operated. Note that diode 26CR15 separates the hold condition of the 26LB relay from the operate condition of the 26EL1 relay so that the 26EL1 relay is free to follow the operational status of the 27EL relay via make contact 27EL-6. Accordingly, relay 26LB is the relay in each link circuit which monitors its busy-idle status.

30 As shown in FIG. 26, ground present on lead SYBC via released break contact 26LB-1 signifies the idle condition of the associated link. Since lead SYBC is multiplied to all link circuits, the absence of ground on the SYBC lead is an indication that all links are busy. The SYBC lead is extended via cable 2110 to the register circuit, FIG. 21, and to the base of transistor 21Q12. When ground is absent from lead SYBC the 21Q1 transistor turns on thereby operating relay 21SYB. Accordingly, the operated condition of the 21SYB relay signifies as discussed hereinbefore that the link circuits are all busy.

35 Turning now to FIG. 27, the operation of relay 26LB opens the link-selecting leads LK- via enabled break

contact 26LB-6. However, transistor 27Q6 will remain on from ground on the SR lead through enabled make contact 27EL-5 resistor 27R29 and diode 27CR13. Thus, the 1st link circuit, once seized by the register, will remain under control of the register until released.

It should be noted that each link circuit is connected to the other link circuits via the respective IA and IB leads such that if battery appears on the IHL- lead of any of the other registers (signifying a turned on 27Q6 transistor in the other link) the 27Q6 transistor of the selected link would remain off even if both LK- leads are grounded. This provision insures that one and only one link is enabled at a time thereby preventing simultaneous connections through two or more links of the matrix network.

2.3 Establishment of a Connection Through the Matrix

Network From the Calling Station to the Register

After the calling station seizes the register the 17A relay in the associated station circuit is operated as discussed above. At this point the register is prevented from being seized by any other station circuit because of the priority chain circuit also described above. However, since the register is common to all of the station circuits there remains the problem of establishing a linkage connection through the matrix switching network from the register to the calling station via the calling station circuit. The circuitry to accomplish this function will now be described, starting with the calling station circuit 1501, FIG. 17.

When relay 17A operates upon seizure of the idle register, ground via released break contact 17B-1, enabled make contact 17A-2 and forward-biased diode 17CR9 is extended via forward-biased diodes 17CR10 and 17CR11 over leads C3 and C4 and cable 1701 to the register 1901, FIG. 19, thereby providing operate grounds for relays (Y3) and (Y4) in selector 1902. It should be noted that the combination of grounds on the C1-C5 leads, FIG. 19, from the station circuit is uniquely associated with each such station circuit in such a manner that the ground combinations are unique for each station circuit. Thus a translation of the respective grounded C- leads results in determining which of the station circuits has seized the register circuit. This translation is accomplished, as will be seen from that which is to follow by the contacts of the (Y-) relays (shown in FIG. 22).

Continuing in FIG. 19, ground extended from the calling station circuit over the C3 lead is extended via forward-biased diode 19CR4 to the resistor and zener diode combination 19R1, 19R2, 19R3, and 19CR7, such that proper voltage potential is available to turn on transistor 19Q1 thereby operating relay 19SR to ground via released break contact 20RB-6. When relay 19SR operates it locks operated via its own make contact 19SR-5, forward-biased diode 19CR16 and resistor 19R5. Relay 19SR operating provides a ground via enabled make contact 19SR-5 and forward-biased diode 19CR17 to operate relay 19CP.

At this time selector 1902 input leads T and R are shorted together via enabled make contact 19SR-2 while the input is effectively disassociated from the link circuits via enabled break contact 19CP-3. Accordingly, the selector 1902 is enabled in the manner

set forth in the above-mentioned Morse patent such that the (B) relay therein becomes operated. Upon the enabling of the (B) relay the (Y-) relays associated with the grounded C- leads operate. Since the 1st station circuit has seized the register 1901 and since the C3 and C4 leads are grounded, relays (Y3) and (Y4) operate. It will be noted that the (Y-) relay operation is forced, or jam set, from the coded leads associated with the station circuit and do not represent translated dialed pulses as described in the above-mentioned Morse patent. The jam setting of the (Y-) relays is necessary at this point to specifically identify the calling station so that the register circuit, in a manner to be detailed hereinafter, may establish a connection through an idle link of the matrix network to the calling station.

Turning now to FIG. 22, the contacts of the (Y-) relays of the selector 1902 from a relay tree in a well-known manner to translate the output of the operated (Y-) relays such that selector input lead SL becomes connected to one out of the ten leads R0 through R9, dependent upon which digit is represented by the (Y-) relays. Selector translation circuit of the Morse patent has been expanded by the addition of transfer relays 22TR and 22T1 controlled by transfer circuit 2203 in such a manner that the 10 outputs (R0-R9) which would normally be available are expanded to an output possibility of 27. The exact selected output is dependent upon the operational status of the transfer circuit and the transfer relays. These elements in turn operate under control of group leads, such as leads GP1 and GP2 from the station circuit (FIG. 17). The station circuits in the group of circuits coded between 3 and 9 have no group lead and thus no transfer relays operate when one of these stations signals a connection. The station circuits coded between 10 and 19 have the GP1 lead grounded thereby controlling the 22TR relay, while the station circuits from the group of circuits coded between 20 and 29 have the GP2 lead grounded thereby controlling the 22T1 relay.

Continuing now in FIG. 22, since the calling station is in the lowest group, the transfer elements are normal and the (Y3) and (Y4) relay contacts are operated (corresponding to the digit 3) in such a manner that lead SL is extended through the selector 1902 to lead R3 and through the transfer circuit 2203 to lead S3. The purpose of using the digit 3 for the 1st station will become clear from that which is contained hereinafter. Lead S3 is associated with the 1st station circuit and thus with the 1st switching matrix. This lead is extended via cable 2210 to FIG. 30 and through the 1st matrix and all three links thereof to FIG. 24.

As shown in FIG. 24, lead S3 is connected to one side 55 of the winding of the 1st link, 1st matrix relay 24A. Lead STB from cable 2410 and FIG. 17 is also connected to the same side of the 24A relay winding and thus any potential on the STB lead is also extended over lead S3. Accordingly, the S3 lead which has been 60 extended from the selector 1902 in response to the jam setting of the (Y-) relays therein corresponding to the calling station now monitors the operational status of the calling station as determined from the voltage potential on the windings of all of the link relays associated with the 1st matrix.

Lead STB is not grounded at this time since the calling station is not currently engaged in a connection.

This condition may be seen in FIG. 17 where lead STB is extended back through resistor 17R14 and diode 17CR17 to released make contact 17B-1 of relay 17B which relay is normal. The aforementioned path is essentially open from ground at this time. This open condition is projected back over the just-described path to the switching matrix, FIGS. 24 and 30, and over lead S3 to the selector circuit 1902, FIG. 22. This condition is then extended over lead SL to FIG. 21 and via released break contact 21SI-1 and resistor 21R1 to the base of transistor 21Q1. Accordingly, transistor 21Q1 does not operate at this time, thereby signifying that the tested matrix is idle.

Returning now to FIG. 19, after the (Y-) relays operate in the selector circuit 1902 the (R) relay operates thereby providing a ground via an enabled make contact of the (R) relay to FIG. 20 over lead RL and through FIG. 20 to FIG. 21 to provide a ground to one side of the winding of relay 21SI. Since transistor 21Q1 is off (as a result of the detected idle condition of the 1st matrix) battery via resistor 21R4 is extended to the base of transistor 21Q4. Ground on the emitter of transistor 21Q4 from lead RL causes that transistor to turn on thereby turning on transistor 21Q5 so as to operate relay 21SI to ground on the RL lead. Relay 21SI locks operated at this time to battery via enabled make contacts 21SR-3 and 21SI-5 and resistor 21R12. Relay 21SI operating provides ground via enabled make contact 21SI-2 and lead SI3 and battery via enabled make contact 21SI-4 over leads SI2, and MXB of cable 2110 to FIG. 25, 26, and 27 to the link circuits.

Since it has been assumed that the 1st link circuit 2501 is the next available link, these potentials on leads SI3, SI2, and MXB are extended thereto via the enabled 27EL and 26EL1 relays therein.

Turning to FIG. 25, battery received on the MXB lead is extended via enabled make contact 26EL1-5 and over lead MXO and cable 2710 (shown in FIG. 27) to FIG. 23 and the vertical multiple MXO through all of the matrix networks associated with the 1st link. Thus, as shown in FIG. 24, the battery on vertical multiple MXO is extended via forward-biased diode 24CR1 and released break contact 24A-6 to one side of the winding of relay 24A. The 24A relay now operates to ground on the other side of the winding which ground has been extended via the horizontal multiple lead S3 (STB). Relay 24F in the matrix also operates at this time. The S3 lead extends, as discussed above, through the 1st matrix and all three links thereof (FIG. 30) and via cable 2210 to FIG. 22 through selector 1902 and the enabled (Y-) and (R) relays therein and over lead SL to FIG. 21 and via enabled make contact 21SI-1 to FIG. 22 and through enabled make contact 22CP1-3 and lead CCP of cable 2211 to FIG. 19 to the summing point of the C1-C3 leads. Since the C3 lead is grounded, ground is extended over the just-described path to operate the matrix relay 24A.

Turning now to FIG. 26 an examination of the 1st link circuit 2501 reveals that battery is extended to lead LKC, cable 2710 from released break contact 27TRB-3, enabled make contact 26LB-3, forward-biased diode 26CR4 and enabled make contact 26EL1-6. This battery is extended to the matrix network, FIG. 23 and 24, to vertical multiple LKC, and via enabled 1st matrix contact 24A-3, FIG. 24, over

horizontal multiple LK back via cable 2410 to the enabling 1st station circuit, FIG. 17.

Continuing in FIG. 17, this battery is extended via lead LK and forward-biased diode 17CR6 to one side of the winding of relay 17B. However, relay 17B remains normal at this time since the other side of the winding is essentially open.

Battery on the winding of relay 17B is also extended via forward-biased diode 17CR23 to one side of windings of each of the relays 17P and 17RV. Relay 17RV operates at this time to ground on the other side of its winding via forward-biased diode 17CR18, enabled make contact 17A-2 and released break contact 17B-1. When the 17RV relay operates ground is extended via enabled make contact 17RV-6 to operate relay 17B. The operation of relay 17B causes the removal of ground from the coding leads C3 and C4 via now enabled break contact 17B-1. Ground is extended via enabled make contact 17B-1, diode 17CR17, and resistor 17R14 over lead STB to hold matrix relays 24A and 24F operated.

Relay 17RV remains operated at this point via enabled make contact 17RV-1 and resistor 17R9 to ground on lead RVG which ground is extended via cable 2410 from the 1st matrix, FIG. 24, and horizontal multiple RVG. As shown in FIG. 24, horizontal multiple RVG is now connected to vertical multiple RVGC via enabled 1st matrix, 1st link contact 24F-1 (the 24F relay operated in parallel with relay 24A). Vertical multiple RVGC is extended via cable 2710 to the 1st link circuit 2501, FIG. 27, to ground via released break contact 27TRB-2. Relay 17B, FIG. 17, also has a holding ground via enabled make contact 17B-1 and diode 17CR5 and thus remains operated. At this time the chaining ground from lead CHI, which had been removed upon operation of relay 17A from lead CHO, is reestablished on lead CHO via now enabled make contact 17B-3 since relay 17A remains operated from ground via enabled make contact 17B-1 and forward-biased diode 17CR4. Thus any other station circuit is now free to bid for the register circuit when the register becomes available.

Turning now to the register circuit 1901, FIG. 19, the removal of ground from the coding leads C3 and C4 from the calling station circuit allows transistor 19Q1 to turn off thereby releasing relay 19SR. Selector 1902 is thereby also released via released make contact 19SR-2 and the now open condition of the T and R leads extending to the selector.

It will be recalled that when relay 19SR operated initially, relay 19CP operated from ground via enabled make contact 19SR-5 and forward-biased diode 19CR17. Relay 19CP remains operated at this time via resistor 19R6 and enabled make contact 19CP-6 to ground via the (B) relay in the selector 1902. Thus, relay 19CP will remain operated until the selector 1902 has released completely, as determined by the release of the (A) and (B) relays therein. Since the 19CP relay does not release until after the complete release of the selector, as just discussed, the T1 lead from the selector which lead extends through break contact 19CP-3, is not cut through to the link circuit until the selector is released.

When relay 19CP releases leads T1 and R1 are cut through to the enabled link circuit via cable 2110 to

FIG. 25, 26, and 27. As shown in FIG. 26, battery is extended through enabled make contact 26EL1-6 to FIG. 25 and forward-biased diode 25CR142 to one side of the winding of relay 25D. The other side of the winding is connected to turned on transistor 25Q7. Transistor 25Q7 is on at this time from loop current flowing through resistor 25R5, through the winding of transformer 25T over lead TC and cable 2710 and through the matrix circuit, FIG. 23 and 24, and enabled make matrix contact 24A-5 and lead T1 and cable 2410 through the 1st station circuit lead T1, FIG. 15, enabled make contact 17A-1 and lead T via leads RT5-1 and cable 411 back to the calling 1st station, FIG. 3, and through the enabled network and dial 301 therein. This loop is completed from network and dial 303 back through the same path to FIG. 15 via the R lead and via enabled make contact 17B-2 and leads R1 through the matrix network, FIG. 23 and 24, and cable 2710 back to FIG. 25, lead RC and through transformer 25T to battery through resistor 25R4. Thus a voltage is present across resistor 25R5 which causes transistor 25Q7 to turn on thereby operating relay 25D. Accordingly, when leads T1 and R1 are extended from the selector circuit via cable 2110 from FIG. 19 a short exists, as shown on FIG. 25, from lead T1 to lead R1 via enabled make contact 25D-2 and released break contact 27DSSC-6. The short across these leads reseizes the selector 1902 in the register 1901, FIG. 19 in preparation for receipt from the calling station, of the code associated with the desired called station.

Continuing now in FIG. 25, tone generator 2502 is arranged in any one of the well-known circuit configurations operable to supply specific tones on a transmission lead in response to voltage potentials, such as ground, applied to an input, the level of the tone being controlled by a selected output resistor, such as resistor 25R1 or resistor 25R2. When the selector 1902, FIG. 19, is reseized ground is provided on lead BDT from the enabled (A) contact, released break contacts 19BDT-1 and 19CP-5. This ground is extended to the link circuit, FIG. 25, and via enabled make contact 27EL-2 to turn on the tone generator 2502. Thus, tone is supplied via resistor 25R1 and over lead TC and back through the previously described linkage connection to the calling station 301 in FIG. 3. Upon receipt of the dial tone the calling subscriber thereupon begins to dial or key pulse the digits associated with the called station.

Upon receipt of the first digit, ground is removed from lead BDT, FIG. 19, thereby inhibiting dial tone, which tone is permanently removed by the operation of relay 19BDT on the first "break" of relay (A) in the selector. The attached register circuit is capable of receiving either dial pulses from the standard rotary dial or TOUCH-TONE type frequency dialing from a key dialer. As has become standard practice in wideband communication whenever a wideband connection is desired the # digit, which digit is generated upon operation of one of the two extra keys of a 12-key TOUCH-TONE type dialer, is operated prior to the operation of the digits of the called station.

Returning now to FIG. 3, the digits corresponding to the called station are transmitted via leads RT5-1 over cable 411 to FIG. 15 and via leads T and R and the now operated make contacts 17A-1, 17B-2, and over leads

T1 and R1 and cable 2410 to FIG. 24 and via the enabled 24A relay of the 1st matrix, 1st link circuit to leads TC and RC, FIG. 23, and via cable 2710 to FIG. 25, the associated link circuit, and via enabled make contacts 27EL-3 and 27EL-4 and capacitors 25C3 and 25C4 over leads TTR1 and TTT1 and cable 2503 to FIG. 19 to the input of TOUCH-TONE adaptor 1904. TOUCH-TONE adaptor 1904 is arranged in any one of the well-known circuit configurations operable to translate frequencies received on a pair of input leads to voltage potentials or grounds on a particular set of leads corresponding to the particular frequencies received. Thus, since the first digit transmitted in the case of a wideband connection is the # digit, a ground is provided on lead PR of TOUCH-TONE adaptor 1904. This ground is extended to FIG. 25 and through forward-biased diode 25CR15 and released break contact 25PP-4 to one side of the 25PP relay winding. The other side of the 25PP relay winding is connected to battery via released break contact 25PP-1 and the lead extending from FIG. 26 and enabled make contact 26EL1-6. The 25PP relay thereupon operates and locks operated to battery via enabled make contact 25PP-1 to one side of the 25PP relay winding while the other side of the winding is connected to ground via enabled make contact 25PP-4 and resistor 25R25 and the lead to FIG. 26 from enabled make contact 26LB-1. The operation of relay 25PP in response to the key pulsing of the # digit from the calling subscriber prepares the selected link circuit in the manner to be more fully detailed hereinafter to accept the dialed digits and to handle the call in the wideband mode such that only two stations may be connected to the same link at the same time thereby ensuring continuous uninterrupted communication between the calling and called party.

Returning now to FIG. 22, the (Y-) relays of selector 1902 are now jam set under control of the TOUCH-TONE adaptor 1904 corresponding to the next two dialed digits from the calling subscriber.

Digressing momentarily and turning to FIG. 25, in the event the calling subscriber has a rotary dial the pulsed digits corresponding to the called station's number will be received by relay 25D which relay is arranged to follow dial pulses. These pulses are communicated to the selector via leads T1 and R1 and make contact 25D-2. Thus as shown on FIG. 19, the inputs T and R of selector 1902 pulses in response to the dialing of the calling subscriber which pulses are operative in a manner set forth in the aforementioned C. E. Morse patent to operate the (Y-) relays in accordance with the dialed digit. Accordingly, the (Y-) relays become set either in response to received dial pulses or in response to received and translated frequencies.

Continuing now in FIG. 22, the contacts of the (Y-) relays form a relay tree as discussed previously such that lead SL is extended through the enabled (R) relay contact and through the enabled (Y-) relay contacts to the proper lead corresponding to the called station which we assume to be the 27th station 201. Since the first dialed or key pulsed digit of the 27th station would be the digit 2, the R2 lead of selector 1902 is extended to transfer circuit 2203 and via released break contacts 22T1-2, 22CP1-2, and 22T-4 and resistor 22R1 to the base of transistor 22Q1. The R2 lead is extended

through the operated contacts of the selector to the break contact of the (R) relay to a source of negative potential. The (R) relay is normal when the (Y-) relays operate because of a slow operate condition. This negative potential turns on transistor 22Q1 turning on transistor 22Q2 thereby operating relay 22T. Relay 22T operating connects the coil of relay 22T1 to lead TG1 which lead is extended via cable 2211 to FIG. 19 to ground via released break contact 19SR-1. Thus, relay 22T1 operates at this time.

Digressing momentarily, it should be noted that since the stations coded from 20 to 29 all begin with the digit 2 and since when the digit 2 is the first digit dialed the transfer relay 22T1 operates as just described, it is imperative that no station other than those coded between 20 and 29 have 2 as a first digit. Also, with respect to those stations coded between 10 and 19 which have the digit 1 as a first number the same transfer function occurs (operation of relay 22TR) with respect to potentials extended on lead R1 and accordingly no station other than those coded between 10 and 19 may begin with the digit 1. Therefore, the 1st station is designated with code 3 and the 2d station is designated with code 4.

Returning now to FIG. 22, when the first digit 2 is dialed the 22T and 22T1 relays operate as discussed above. Accordingly, ground which had been extended from the register circuit, FIG. 19, released break contact 19SR-1 over lead TG1 and cable 2211 and through released break contact 22T-2 over lead TG is now broken via enabled break contact 22T-2. Following lead TG in cable 2211 back to FIG. 19 it will be seen that the (Y-) relays, which operated as a result of the dialed digits, are held operated from ground on the TG lead. Accordingly, after receipt of the first digit the ground is removed by the transfer circuit 2203 thereby releasing the (Y-) relays and preparing the selector circuit for receipt of the second digit which in this case would be the digit 9 since all stations have codes two numbers higher than their equipment designations.

Upon receipt of the digit 9, lead SL is cut through the selector 1902, enabled contacts (R) and (Y-), and released break contact 22TR-2 and over lead R9 to transfer circuit 2203 and via enabled make contact 22T1-13 and lead S29 of cable 2210 to the 27th matrix, FIG. 29, horizontal multiple S29. Thus the S29 horizontal multiple is extended, as shown in FIG. 24 to the coil of the matrix relays associated with the 27th matrix.

Turning again to FIG. 22, the SL lead which was cut through in the manner just described is extended to FIG. 21 to the busy-idle detector and to the base of the 21Q1 transistor therein. Busy-idle detector 2101 again performs a busy-idle test of the called matrix 27. Since the called matrix is assumed idle ground is not present on the matrix relays. Thus condition is extended back through lead S29 and FIG. 22 to busy-idle detector 2101 in FIG. 21 which busy-idle detector functions in the exact manner as detailed hereinbefore.

Continuing now in FIG. 21, since the matrix relay corresponding to the called station is idle, transistor 21Q1 remains off and relay 21SI operates. Ground is thereby extended via released break contact 22CP1-3 of transfer circuit 2203 and enabled make contact 21SI-1 of busy-idle detector 2101 back through the

5 selector 1902 and transfer circuit 2203, FIG. 22, to operate the matrix relay associated with the 27th station (code 29) and with link 1. It is the link 1 relay as opposed to the relays associated with links 2 and 3 which operates at this time because of the negative potential on lead MXO via cable 2710 from the enabled first link circuit, FIG. 25, in the manner discussed previously.

Continuing now in FIG. 23, negative potential which 10 is on the horizontal multiple LKC in the manner discussed previously is extended through the now enabled matrix relay contact (corresponding to enabled make contact 24A-3, FIG. 24) and over the associated LK lead to FIG. 14 to operate the 17B relay in the 15 called 27th station circuit which circuit is arranged in the exact manner as is the 1st station circuit, FIG. 15, 16, and 17. For convenience, further reference to the 20 27th station circuit 1401 will be made with respect to the 1st station circuit 1501 with the understanding that the following described circuit operations occur in the 27th station circuit. Thus, negative potential is 25 extended via lead LK shown in FIG. 17 through forward-biased diode 17CR6 to one side of the 17B relay winding. The other side of the winding is extended through released break contacts 17A-2 and 17B-1 to ground. The 17B relay now operates and locks operated from ground via enabled make contact 17B-1 and forward-biased diode 17CR5. Since in the called station the 30 17A relay is normal, ground is also extended at this time via enabled make contact 17B-1, forward-biased diode 17CR17, and resistor 17R14 over lead STB to the 27th switch matrix thereby holding the operated 24A and 24F relays in link 1 associated with the called 35 27th station. Since this call is a wideband call as discussed previously, ground is on lead P of both the calling and called station circuits, FIG. 17, from the 1st and 27th matrix networks and enabled make contact 24A-1 and vertical multiple PC and cable 2710 from the 1st link circuit, FIG. 27, and released break contact 40 26TD1-3 and enabled make contact 25PP-3.

Continuing now in FIG. 17, ground on lead P 45 operates relay 17P to battery which has been extended via forward-biased diodes 17CR23 and 17CR6 and the LK lead as previously discussed. At this point the only 50 relays operated in the called station circuit are relays 17B and 17P. Thus, as shown on FIG. 16 positive potential is extended via enabled make contacts 17P-3 and 17B-6 and released break contact 17A-6 and lead LH and cable 1601 to the associated hold circuit which in the case of the 27th station circuit is hold circuit 1801 and through the hold circuit and released break contact 18H-2 and the associated L5- lead which in 55 this case would be L5-27 and cable 411 back to the called 27th station 201 and via the forward-biased diode 4P1- lead which in this case would be 4P1-27 to illuminate the red line 5 lamp therein at the 27th station.

60 Turning now to FIG. 27, ringing voltage is applied to the called line from ring source 2701 which ring source is arranged in any one of the well-known circuit configurations operable to provide periodic ringing voltage on a line via lead IRV to FIG. 14 and the 27th station circuit 1401. The path through the 27th station circuit may be seen in FIG. 15 with respect to the 1st station circuit 1501 where the ring source voltage on lead IRV

is extended via enabled make contact 17B-4, released break contact 17A-4, and enabled make contact 17P-6, and the associated TR5- lead which in this case is TR5-27 and cable 411 back to FIG. 2 to enable the tone ringer in the called 27th station 201. It will be noted that the tone ringer is enabled at this point as opposed to the enabling of the bell ringer as an indication that a PICTUREPHONE call has been directed to that station.

2.4 Extension of System Tones to the Calling Station

After dialing has been completed, either one of two tones may be returned to the calling party. Audible ringing tone when the called station is idle and audible busy tone when the called station is busy. In addition, when dialing has not been completed within a certain interval permanent signal is returned to the calling subscriber. The extension of these tones through the switching matrix will now be discussed.

Turning to FIG. 21, it will be recalled that relay 21SI operated upon detecting the idle condition of the 27th matrix. Also at this time relay 19CP is unoperated since that relay operates only when the calling station first seizes the register circuit and releases, as discussed above, prior to receipt of the digits associated with the called station. Thus, at this point, ground is extended via enabled make contact 21SI-2, and released break contact 19CP-4 over lead SI1 and cable 2110 to FIG. 26 and via forward-biased diode 26CR10 and enabled make contact 26EL1-2 and released break contact 26TR1-6 to operate relay 26TR1. The 26TR1 relay locks operated through enabled make contact 26TR1-6, resistor 26R26, enabled make contact 26R-4 to ground via enabled make contact 26LB-1. Relay 26R is operated at this time from turned on transistor 26Q6 which transistor has been turned on by battery extended to its base via resistors 26R161, 26R181, enabled make contact 26EL1-1, and lead RNC from FIG. 20. Battery is provided on lead RNC as shown in FIG. 20 at the completion of the calling interval or at the expiration of 12 seconds as determined from the seizure of the register. The circuitry for providing this battery will now be discussed.

When relay 19SR, FIG. 19, operates at the beginning of a call a control path to relay 20RB is established. The path used to initiate the operation of relay 20RB is from ground through enabled make contact 19SR-6, resistor 20R24, and turned on transistor 20Q8 which transistor completes an operate path for relay 20RB. Relay 20RB operates via a lead from relays (A) and (B) of selector 1902 when that selector is seized as herein previously described. When relay 20RB operates as described, a positive transient is coupled through capacitor 20C1 via enabled make contact 20RB-6 causing transistor 20Q6 to turn off for approximately 12 seconds as determined by capacitor 20C1 and resistor 20R20. Break contact 20RB-2 and resistor 20R21 provide a current path to maintain transistor 20Q6 saturated when the register is idle. Transistor 20Q6 turning off turns on transistor 20Q7 which in turn turns on transistor 20Q8 thereby holding relay 20RB in the operated state when relay 19SR releases. During the release reseizure sequence of the selector relay 20RB remains operated because of the slow release network composed of capacitor 20C2 and resistor

20R26. If dialing has not been completed within the nominal 12-second timing period transistor 20Q6 turns on causing transistor 20Q7 to turn off thereby causing transistor 20Q4 to turn on. Transistor 20Q4 turns on from battery via resistor 20R16 while ground is on its emitter via varistor 20RV4 from selector 1902, FIG. 19. Ground is thereby supplied to lead PS which ground causes permanent signal tone, as will be described hereinafter, to be returned to the calling subscriber. Transistor 20Q4 turned on also turns on transistor 20Q5 from ground via forward-biased diode 20CR30 and resistor 20R15 to the base of transistor 20Q5. Transistor 20Q5 turning on extends battery via forward-biased diode 20CR37 and lead RNC to the enabled link circuit, FIG. 26, to operate the 26R relay therein in the manner previously discussed.

Returning to FIG. 20, when transistor 20Q7 turned off transistor 20Q8 also turned off thereby allowing relay 20RB to release in approximately 90 milliseconds. When relay 20RB releases, ground is removed from lead SR, FIG. 21, causing the enabled link circuit to release. Also selector 1902 in FIG. 19 is released at this time via released make contact 19SR-2.

In a situation where dialing is completed prior to the timeout just described, ground is extended from selector 1902, FIG. 19, over the enabled (B) and (R) contacts therein and lead RL to FIG. 20 and via release break contact 19CP-6, resistor 20R27, diode 20CR16, and resistor 20R14 to turn on transistor 20Q5 thereby extending battery over lead RNC so as to operate the 26R relay, FIG. 26, in the manner discussed above. The appearance of battery on lead RNC also causes current to flow through resistor 20R18 thereby effectively shortening the timing period at the base of transistor 20Q6 to approximately 100 ms. It should be noted, as shown in FIG. 20, the ground on the base of transistor 20Q5 from the selector circuit, FIG. 19, does not extend over the PS lead at this time because of the reverse-biased condition of diode 20CR30.

Continuing now in FIG. 21, in a situation where the called station is busy, negative potential will be present on lead SL to the busy-idle detector 2101, FIG. 21, causing transistor 21Q1 therein to turn on thereby turning on transistors 21Q2 and 21Q3. Transistor 21Q3 turning on extends ground via lead SB to the associated link circuit, FIG. 26, thereby enabling relay 26TR1 via forward-biased diode 26CR11, enabled make contact 26EL1-2 and released break contact 26TR1-6 while at the same time also enabling relay 26TR2 via forward-biased diode 26CR12, enabled make contact 26EL1-3 and released break contact 26TR2-1. Thus in a situation where a busy condition of the called station has been detected both of the relays 26TR1 and 26TR2 operate.

The generation of the actual tones transmitted back to the calling subscriber is accomplished by tone generator 2502 shown in FIG. 25 which tone generator operates in the manner previously described in response to ground potentials supplied on its input lead. The precise tone which is transmitted is controlled by the operational combination of the relays 26TR1 and 26TR2 such that when relay 26TR1 is operated singly, audible ringing tone is returned to the calling subscriber. This is accomplished by interrupted ground supplied by interrupter 25IN and enabled make

contact 26TR1-3, released break contact 26TR2-6 to the input of tone generator 2502, the output of which is connected to lead TC via resistor 25R1 in the manner previously discussed. When both of the TR1 and TR2 relays are operated, which is the case when the called station is busy, pulsating ground is supplied from interrupter 25IN via enabled make contacts 26TR1-2 and 26TR2-6 to the tone generator 2502. It should be noted that the interruption rates of the aforementioned grounds are distinct thereby providing busy tone and ringing tone. When relay 26TR2 operates alone, thus signifying a time-out condition and a permanent signal, steady ground is extended via released break contact 26TR1-2, enabled make contact 26TR2-6 to tone generator 2502. At this time the output of the tone generator is connected via released break contact 26TR1-4 and enabled make contact 26TR2-7 and shunt resistor 25R2 to lead TC and back to the calling subscriber.

Since it is advantageous at the completion of the dialing interval to provide immediate tones to the calling subscriber provision has been made to begin the tone generation period immediately at the completion of dialing without regard to the status of the interrupter contacts. This function is accomplished as a result of the operation of the 26R relay previously described. As shown in FIG. 25, transistor 25Q2 turns on upon the operation of relay 26R thereby turning on transistor 25Q3 so as to operate relay 25IMR. The 25IMR relay remains operated under control of capacitor 25C2 for approximately one-half second. During the interval in which the 25IMR relay is operated steady ground is applied via enabled make contact 25IMR-1 to tone generator 2502.

2.5 Connection to the Called Station

If the called party answers within thirty seconds, a ground-going transient will appear on lead RTC, FIG. 27, from the matrix associated with the called station. This transient is generated by transistor 16Q3 in FIG. 16 which transistor momentarily turns on under control of capacitor 16C1 and resistors 16R6 and 16R7 when the called station goes off-hook in the manner previously described.

Returning now to FIG. 27, momentary ground on lead RTC is extended to FIG. 26 and resistor 26R9 to turn on transistor 26Q4. Battery is then extended via turned on transistor 26Q4 and resistor 26R11 to turn on transistor 26Q5. Transistor 26Q5 would turn off at the end of the transient except that a feedback path is provided via enabled make contact 26R-2 and resistor 26R12. When transistor 26Q5 turns on transistor 26Q6 turns off. Thus, transistor 26Q5 remains turned on by current flow from battery through the winding of relay 26R until that relay releases completely.

It will be recalled that when the register finished processing the connection the ground was removed from the SR lead, FIG. 21. Thus, as shown in FIG. 26, relay 27EL releases thereby also releasing relay 26EL1. At this point the register is free to handle other connections while the active link circuit changes from the busy mode to the unavailable mode with relay 26LB therein operated. Relay 26LB will remain operated as long as at least one station remains connected to the associated link. This follows since relay 26LB is controlled from

ground extended from FIG. 25, diode 25CR14, and turned on transistor 25Q7 which transistor remains on under control of current flowing through the loop circuit from the subscriber stations and transformer 25T.

Stations which do not answer within a certain interval are released. The release is accomplished as follows. When relay 26EL1 releases, a negative potential is extended via released break contact 26EL1-6 thereby causing a negative transient via resistors 26R15 and 26R16 and capacitor 26C4, diode 26CR3 to turn transistor 26Q1 off and 26Q2 and 26Q3 on actually before the release of make contact 26EL1-6 thus maintaining battery on lead LKC via enabled make contact in 26LB-3 and released break contact 27TRB-3. At this point the negative potential on lead LKC is dependent upon the time constant determined by capacitor 26C4 and register 26R16 which time constant is approximately thirty seconds. At the completion of the timed interval transistor 26Q1 turns on thereby turning off transistors 26Q2 and 26Q3 removing a negative potential from lead LKC thereby releasing the station circuits associated with stations which have not gone off-hook within the timed interval.

Since the register is now free to handle other connections and since the 1st link circuit is unavailable at this point provision must be made for the register to seize an available link circuit upon the initiation of the next calling connection. As shown in FIG. 27, since relay 26LB remains operated while the link circuit is in the unavailable mode, the LK- leads to transistor 27Q6 are opened via enabled break contact 26LB-6. Prior to the point where the 27EL relay released, ground was present via enabled make contact 27EL-5 and resistor 27R29 to maintain transistor 27Q6 on. When the 27EL relay releases, as discussed above when the register is finished processing the connection, the 27Q6 transistor turns off thereby removing the battery potential from lead IHL1 and thus allowing the pulse shaper 2103 in the register 1901, FIG. 21, again to begin pulsing causing the binary counter 2102 to again provide unique outputs sequentially until an available link is found. The counter will continue to pass over the 1st link circuit during such time that the associated link is busy because of the operated condition of the 26LB relay and enabled break contact 26LB-6 therein.

2.6 Transmission Communication Between the Called and Calling Stations

Turning now to the 1st station circuit (calling station), FIG. 17, it will be recalled that battery appeared on the LK lead upon establishment of the calling connection to the idle link. At that point, relays 17RV and 17B operated in the calling station circuit. As shown in FIG. 15, the video quad leads VOT1, VOR1, VIT1, and VIR1 are reversed at this time under control of the enabled transfer contacts 17RV-4, 17RV-3, 17RV-5, and 17RV-2. With respect to the called party, it will be recalled that when the called party went off-hook in response to an incoming call directed thereto the 16Q4 transistor turned on thereby enabling the 17A relay, FIG. 17, in the called station's circuit. Since in the called station circuit, as shown in FIG. 17, the 17B relay operated prior to the operation of the 17A relay,

the 17RV relay therein remained normal because of the enabled condition of break contact 17B-1. Thus, as shown in FIG. 15, the video quad leads VOT1, VOR1, VIT1, VIR1 of the called station are not reversed and are extended directly through the called station circuit to leads VOTP, VORP, VITP, and VIRP, respectively.

Also it will be recalled that the 16Q2 transistor in both the calling and called station circuits turned on upon the respective stations going off-hook. Accordingly, the V leads from each of these station circuits have grounds thereon which grounds are extended over cable 2410 to the respective matrix networks, FIG. 23 and 24, to operate the 24V matrix relays therein associated with the 1st link 1st station, and 1st link 27th station. It is the 1st link 24V relays which operate as opposed to the 24V relays (not shown) associated with the other links, because of the operated condition of the 1st link 24F relays and particularly contact 24F-5 thereof.

Turning now to FIG. 16, if the station circuit is currently in a PICTUREPHONE mode relay 17P will be operated in the station circuit and transistor 16Q4 would be on. Accordingly, battery would be extended from 16Q4 to enabled make contact 17P-5, resistor 16R4 to turn on transistor 16Q2. Thus ground would be extended on lead V and also ground would be extended to FIG. 15 through resistor 15R3 turning on transistor 15Q1. Battery from the emitter of transistor 15Q1 would then be extended via resistor 15R2 over lead TOS1 and cable 411 back to FIG. 4 to the video control VC1-1 of the associated video set, such as video control VC1-1 of video set 401. Video control VC1-1 is arranged such that when battery has been extended thereto over the TOS- lead transmission is possible from associated camera C1-1 and to the associated screen S1-1.

Turning now to FIG. 4, communication from the camera C1-1 of the 1st video set 401 is possible via pad P-1, video control VC1-1 over the video output leads VOT1 and VOR1 and cable 411 to FIG. 12 and through the picks voice operated switch 1201 for the 1st station and the released break contacts therein and over leads VOTP and VORP to FIG. 15 to the 1st station circuit 1501 and via the enabled 17RV contacts 17RV-4 and 17RV-3 which contacts act to reverse the transmission path and out of the 1st station circuit via leads VIT1 and VIR1 and over cable 2401 to the 1st matrix 1st link connection and through enabled matrix contacts 24V-5 and 24V-4 and via the vertical multiple VITC and VIRC to the 27th matrix and via the enabled 24V relay associated with that matrix and the associated horizontal multiple leads to the 27th station circuit shown in FIG. 14 and, as detailed in FIG. 15, over the VIT1 and VIR1 leads therein. Since in the called station circuit the 17RV relay is normal the transmission is extended through the 27th station circuit and over leads VITP and VIRP back to the called station via the associated picks voice operated switch for the 27th station 1101 shown in FIG. 11 and through the normal break contacts therein and over leads VIT1 and VIR1 (shown in FIG. 12) and cable 411 back to the 27th video set 202 shown in FIG. 2. Accordingly, transmission originating in the calling video set is received by the screen of the called video set and transmission originating from the camera of the 27th video

set is received by the screen of the 1st video set via a pair of leads extended in the same manner between the video sets as just discussed.

It should be noted at this point that the video communication between the calling and called station was extended through a picks voice operated switch as shown in FIG. 11 and 12. These switches are necessary for video conference connections and in situations where such connections are not desirable these switches may be eliminated and the leads extended in a straightforward manner without regard to the contacts therein.

2.7 Direct Station Signaling (DSS)

Assume now that a calling station is connected to a called station via the 1st link circuit. Also assume that the two stations are in PICTUREPHONE communication with each other and that the calling station desires to establish a conference connection between the two communicating stations and a third station which we will assume to be the 2d system station. Also assume at this point that the calling station has a direct station selection (DSS) key associated with the 2d station which station is coded 4. It is to be further assumed that the video conferencing facilities are not available and thus the added station may only be added in an audio mode.

The calling subscriber at the 1st station, in order to initiate such a connection, operates the desired DSS key, such as key 4DSS.

As shown in FIG. 4, one side of the operated 4DSS key at the 1st station circuit is extended over lead DSS and cable 411 to the matrix associated with the calling station which in this case is the 1st matrix shown in FIG. 24. This lead is extended through the horizontal multiple DSS of 1st matrix and the enabled 24F-4 contact to the vertical multiple DSSC, FIG. 23, and over cable 2710 to the 1st link circuit, FIG. 27, and via resistor 27R19 to the base of transistor 27Q7. Ground on the emitter of transistor 27Q7 causes current to flow from the base emitter junction thereof over the just-described path and lead DSSC through the 1st link, 1st matrix, back to the calling station, FIG. 4, and through the now enabled 4DSS key over lead DSSK to the station circuit associated with the 2d station. Since this station circuit has not been detailed, the following description will be given with respect to the 1st station circuit shown in FIGS. 15, 16 and 17, with the understanding, however, that the DSSK lead from the DSS key in the calling 1st station is actually connected to the 2d station circuit.

Turning now to FIG. 17, the current flowing through the now enabled DSS key over lead DSSK is communicated to the register via diodes 17CR10 and 17CR11 which diodes are associated with the C-leads uniquely associated with the 2d station.

Turning now to FIG. 19, the grounds enter the register circuit via the C-leads and are communicated to operate the respective (Y-) relays in the selector 1902 in the same manner as for a calling station. It should be noted, however, that the (Y-) relays which will operate, correspond to the (Y-) relays associated with the 2d station, which in this case is a called station, which 2d station has been direct signal selected from a 1st station which is the calling station.

At this time the current flowing on the C- leads is limited by resistor 27R19, FIG. 27. Because of this current limitation the voltage developed across resistor 19R1 is insufficient to cause transistor 19Q1 to turn on through zener diode 19CR7 and resistor 19R2. Transistor 19Q1 remaining off at this time maintains relay 19SR in a released condition. Accordingly, at this point the register circuit has not been seized and thus, although grounds have been supplied to the selector circuit 1902 the (B) relay therein has not operated and therefore the selector remains idle. This follows because it has not as yet been determined whether or not the register circuit is available to handle this call at this time.

Returning now to the 1st link circuit, FIG. 27, current flowing through transistor 27Q7 causes ground to be supplied via diode 27CR6 to one side of the 27EL relay winding. Ground is also supplied via resistor 27R25, diode 27CR61 and resistor 27R22 to the base of transistor 27Q8, thereby turning on transistor 27Q8 and supplying battery to one side of the 27DSSC relay winding. The other side of the 27DSSC relay winding is extended via diode 27CR7, released break contact 27DSSC-1 and lead OP1 and cable 2110 to register circuit FIG. 20 to the collector of transistor 20Q3. If the register is idle, transistor 20Q3 will be on and a ground will be supplied via released break contact 20RB-1, thereby operating relay 27DSSC in FIG. 27.

It would be noted that in the event the register circuit is currently busy, the 20RB relay therein would be operated in a manner previously described thereby removing ground from the 20Q3 transistor via enabled break contact 20RB-1 so as to maintain the 27DSSC relay in the link circuit normal. Ground removed from the 20Q3 transistor also removes ground at this time from lead OP which ground it will be recalled was extended to the station circuits to operate the request relays therein. Removal of this ground prevents any other station circuit from selecting a register while the register is busy thereby preventing race conditions.

Returning again to FIG. 27, the enabling of relay 27DSSC causes that relay to lock operated via its own enabled make contact 27DSSC-1 and lead DSSL to the register circuit, FIG. 20, to current flowing from the emitter of transistor 20Q2 via resistor 20R9. The current flowing through transistor 20Q2 clamps transistor 20Q3 off, thereby removing ground from the OP and OP1 leads. Again returning to FIG. 27, transistor 27Q7 turning on extends a ground via enabled make contact 27DSSC-2 and resistor 27R21 to turn on transistor 27Q6. Transistor 27Q6 turning on provides negative potential to one side of the 27EL relay winding. The other side of the 27EL relay winding is connected via diode 27CR6 to the ground extended from turned on transistor 27Q7. Accordingly, at this point the first register circuit becomes enabled via the enabling of relay 27EL and the enabling of relay 26EL1 in the manner previously described.

At this point the ground which had been extended from the base of transistor 27Q7 now bypasses resistor 27R19 via enabled make contacts 27EL-1 and 27DSSC-5. This essentially solid ground is now fed back through the 1st link, 1st matrix to the calling station and from the operated DSS key therein to the called station and through the C- leads therein to the

register circuit, FIG. 19. The 19Q1 transistor now turns on signifying a service request thereby operating relay 19SR and seizing the selector 1902 in a manner previously described. At this point the (Y-) relays in the selector operate and the call progresses in the manner previously described for an initiated call with the exception now that the link circuit on which the called station is to be connected is the link circuit previously used by the calling station and is not a new link circuit. Accordingly one basic difference between this type of call and an originating call is that the selector 1902 must be seized only once in response to the calling station. This follows since dialing will not be forthcoming from the calling station. The circuitry for preventing a reseizure is as follows as shown on FIG. 27.

Relay 27DSSC is slow to release due to the charge remaining on capacitor 27C6 which charge holds transistor 27Q8 on after the release of the enabling ground from transistor 27Q7 which enabling ground is removed upon the release of the DSS key in the calling station. As shown in FIG. 25, it will be recalled that the selector was reseized by the shorting together of the T1 and R1 leads via enabled make contact 25D-2 and released break contact 27DSSC-6. Since the 27DSSC relay is operated and is slow to release the leads T1 and R1 are not shorted on a direct station signaled call therefore preventing the selector from becoming reseized on such a call.

Turning now to FIG. 22, when the (Y-) relays operate in selector 1902 as a result of ground being extended from the 2d station the SL lead is extended through selector 1902 and over lead R4 through transfer circuit 2203 and released break contact 22T1-3 therein and over lead S4 and cable 2210 to the 2d matrix and a busy-idle test is performed by busy-idle detector 2101, FIG. 21, in the manner previously described. When the 21SI relay in the detector operates at the conclusion of the test the SL lead is extended via enabled make contact 21SI-1 and lead SSG through the enabled make contact 22CP1-3 of transfer circuit 2203 and lead CCP of cable 2211 to FIG. 19 and ground at the summing point of the 19Q1 transistor. This ground is extended to operate the 24A and 24F relays in the second switch matrix (not shown) which matrix is associated with the 1st link circuit, FIGS. 23 and 24. It is the 24A and 24F relays of the 1st link which operate since only that link has battery on its MXO vertical multiple. This may be seen from 1st link circuit 2501, FIG. 25, where lead MXO is extended through enabled make contact 26EL1-5 over lead MXB to the register circuit, FIG. 21, to battery via enabled make contact 21SI-4. Thus, only when the register circuit is associated with the 1st link circuit will the relays thereof operate in the matrix network.

Accordingly, at this point the 2d station circuit is cut through to the 2d matrix in the same manner as the original called station was cut through and ringing potential is applied to the called station in the same manner as was discussed for the original called station. When the 2d station goes off-hook in response to the ringing potential applied thereto the 16Q4 transistor in the associated station circuit, (not shown, but identical to that detailed in FIG. 16) turns on in the manner previously described. However, the 17P relay is not operated in the 2d station at this point and therefore

transistor 16Q2 remains off thereby maintaining lead V high such that the 24V relay in the 2d matrix is not operated and may not become operated at this time. Accordingly, video transmission is not possible from or to the 2d station at any time during the call.

Turning now to FIG. 17, the 17P relay cannot operate in the 2d called station because of the absence of ground on lead P. This absence of ground can be seen by tracing lead P back through the horizontal multiple associated with station P (not shown but detailed in FIG. 24 with respect to the 1st station). The horizontal multiple P is extended through enabled make contact 24A-1 of the enabled matrix to the vertical multiple PC to FIG. 23 and over cable 2710 to FIG. 27, lead PC to break contact 26TD1-3. Relay 26TD1 operated when the 27EL relay released after the original connection. At that time the 27EL relay was normal while the 25PP relay was operated thereby supplying ground via released break contact 27EL-6, and released break contact 26TD1-4 to operate relay 26TD1. When relay 26TD1 operated it locked operated through enabled make contact 26TD1-4 and resistor 26R261 to ground via enabled make contact 26LB-1.

Accordingly, at this point the 2d station is connected to the 1st link to which link both the 1st and 27th stations have already been connected. The talking path from the 2d station is extended through the 1st link, FIG. 23 and 24, and vertical multiples TC and RC to all the connected stations and to the 1st link circuit, FIG. 25, where battery and ground potentials are applied via leads TC and RC and transformer 25T.

2.8 Register Recall

In the preceding sections it was discussed how a calling subscriber connected to the link circuit may, by operation of a direct station signaling key at the calling station, establish a connection directly to a called station without dialing the digits associated with the called station. As discussed, the selector 1902 of the register circuit was forced by the coding leads of the called station such that the called station was connected to the previously established link as though the called station had been a calling station. In the event the station to be added to the conference is not associated with a direct station signaling key at the calling station the register must be recalled by the calling station and the digits corresponding to the code of the called station must be transferred thereto. The following description will discuss the circuitry associated with this feature.

Turning now to FIG. 4, when it is desired to establish a connection from a 1st station already established to a link the register recall key, such as key 4RRC, is enabled. The DSS lead connected to one side of the register recall key, which lead has been discussed previously, is extended through the calling station to the link to which that station is currently attached. Thus the DSS lead extends at this point back to the 1st link to the base of transistor 27Q7 therein. The resistance ground potential on the DSS lead is then extended to the enabled 4RRC key contact and over lead RRC, cable 411, to FIG. 20 and through diode 20CR19 to the summing point of transistor 19Q1. This ground, being resistance ground as discussed previously, is not sufficient to cause transistor 19Q1 to turn on and thus relay 19SR remains normal.

Continuing in FIG. 20, if the register is idle at this time transistor 20Q3 is on and ground is extended via released break contact 20RB-1 through transistor 20Q3 over lead OP1 and cable 2110 to the link circuits, 5 FIG. 27, and via the released break contact 27DSSC-1 and diode 27CR7 to one side of the relay 27DSSC winding. Since the register recall key is operated, current flowing on the DSSC lead in the manner previously discussed turns on transistors 27Q7 and 27Q8 thereby causing relay 27DSSC to operate at this time. Accordingly, the resistor 27R19 is removed from the circuit via enabled make contacts 27E1-1 and 27DSSC-5 also in the manner previously discussed. This essentially solid ground is extended from the 1st link circuit through the matrix and through the calling 1st station circuit to the calling 1st station and through the operated register recall key to the register circuit over lead RRC, thereby turning on transistor 19Q1 and operating relays 19SR and 19CP in the manner previously described for a calling connection.

Since ground has not been extended from the calling station over the C-leads to the register circuit, the (Y-) relays in selector 1902 remain normal at this time.

When the 19SR relay operates, ground is extended via enabled make contact 19SR-5 to FIG. 20 to the emitter of transistor 20Q9 via resistor 20R2. The base of transistor 20Q9 is being driven via lead RRC and thus that transistor 20Q9 turns on. Transistor 20Q9 is arranged to hold relay 19SR operated for a period of time after the release of the register recall key. This holding time is necessary in order to permit a continuous short to exist across the T and R leads between the 25 time the 19SR relay operates and the time when 27DSSC relay in the associated link circuit releases. The purpose of this continuous period is to ensure that once the selector is seized it remains seized for a period of time sufficient to ensure that the 27DSSC relay 30 releases thereby allowing dialing from the calling station to proceed in a straightforward manner. Thus, when the register recall key is released transistor 27Q7 turns off in the link circuit thereby beginning the timing interval for the release of the 27DSSC relay. At the end of the timing interval transistor 27Q8 turns off thereby releasing relay 27DSSC. Accordingly, as shown in FIG. 25, the T1 and R1 leads are again shorted via enabled make contact 25D-2 and released break contact 27DSSC-6. Continuing in FIG. 19 at the end of the timing interval determined by capacitor 20C9 and resistor 20R28 transistor 20Q9 turns off thereby turning off transistor 19Q1 and releasing relay 19SR. When relay 19SR releases the T and R leads of selector 1902 are cut through to the 1st link circuit and a short is maintained thereon via enabled make contact 25D-2 and released break contact 27DSSC-6. Dial tone is now returned to the 1st link in the manner previously discussed. When TOUCH-TONE dialing takes place, 45 the TOUCH-TONE adaptor 1904 translates the frequencies, thereby operating the (Y-) relays in the selector. The operated ones of the (Y-) relays correspond to the code of the called station. Thus at the completion of the dialing interval the called station is connected to the link in the same manner as previously described for a called station except that video transmission is not possible to or from the added party.

2.9 Hold Circuit

When it is desired to place an established connection on hold either party may operate the hold key thereat. Assuming that the 1st station hold key is operated as shown in FIG. 3 ground would be extended via enabled make contacts 3SW1-8 and 3HLD1-2 over lead H-1 and cable 411 to FIG. 18 to the hold circuit associated with the 1st station which in this case would be 1st hold circuit 1803. The ground extended via lead H-1 is extended through released break contact 18H-3 and resistor 18R1 to turn on transistor 18Q1. Transistor 18Q1 turning on extends battery through resistor 18R3 to turn on transistor 18Q2 thereby operating relay 18H to ground on lead HG which ground is present on lead HG from the associated station, FIG. 17, and diode 17CR15 via enabled make contact 17B-1. The 17B relay in the station circuit is operated at this time since the associated station is connected to a link circuit.

Continuing in FIG. 18, ground is extended from lead HG to hold transistor 18Q1 operated via enabled make contact 18H-3. Ground is also extended via diode 18CR4 over the AH lead and cable 1601 to FIG. 16 thereby maintaining transistor 16Q4 on irrespective of the ground condition of the A5-1 lead from the associated station. When the hold key at the 1st station is operated the pickup key automatically releases thereby removing ground from the A5-1 lead in a straightforward manner. The tip and ring leads at the station are thereby interrupted as well known.

Continuing in FIG. 18, the operation of relay 18H extends to ground via enabled make contact 18H-4 and diode 18CR1 over lead V1 of cable 1601 to FIG. 16 to the base of transistor 16Q2 thereby clamping transistor 16Q2 off so as to remove ground from the V lead thereby causing the 24V relay in the 1st matrix to release thus inhibiting the video connections through the matrix. Ground removed from the V lead also removes the ground from lead TOS1 by turning off transistor 15Q1 thereby maintaining the video set at the subscriber station in an inoperative condition.

Returning again to FIG. 18, lamp potentials are extended to the 1st station via lead L5-1 in the manner previously described. The potentials originating in the station circuit are broken by disabled transfer contact 18H-2 and these potentials are now under control of the interrupter 18IN such that in a non-PICTUREPHONE call (relay 18PP normal) negative potential is extended in a pulsing manner thereby operating the white lamp at the station. If the call is a PICTUREPHONE call the 18PP relay would be operated thereby extending pulsating positive potential to flash the red lamp at the station. The 18PP relay is operated on PICTUREPHONE calls from ground extended over lead HP and cable 1601 from FIG. 17 and the enabled make contact 17P-1 therein.

Accordingly, upon the enabling of the hold key the audio leads are opened in a straightforward manner; the video connection is released via the release of the video matrix contacts in the matrix; and appropriate lamp signals are provided to the station.

When the station again desires to resume the connection the pickup key is operated and ground reappears on lead A5-1, FIG. 15. This ground is extended via lead A of cable 1601 to the associated hold circuit and

through forward-biased diode 18CR2 to clamp transistor 18Q2 off. Relay 18H thereupon releases and the connection is restored to normal.

2.10 Add-On Transfer

In the previous sections we discussed the situation where a 1st station connected to a 27th station via the 1st intercom link desired to add a third or a fourth station to the conference network via the intercom link. Now we shall discuss the situation where the 1st station is in communication with the 27th station over the 1st intercom link and at the same time it is desired to add a third party to the connection which third party is available over a PBX line circuit, such as line circuit 302 shown in FIG. 3.

Turning now to FIG. 3, in the situation where it is desired to establish a three-party conference between the 1st station 301, line circuit 302 to the PBX facility 20 and the previously connected 27th station 201, FIG. 2, which station has been previously connected to the 1st station via the 1st intercom link, the 27th station is placed on hold by the subscriber at the 1st station 301. Since the PBX line circuit 302 is associated with line 4, pickup key 3PU4 thereby extending a ground through enabled make contact 3PU4-3 over lead A4-1 to the line circuit 302, the line circuit responds to a grounded A4-1 lead in the well-known manner such that a connection becomes established to the PBX facility. Transmission is extended at this time from the 1st station network and dial 303 via enabled switchhook contacts 3SW1-6 and 3SW1-7, 7 and enabled pickup key contacts 3PU4-1 and 3PU4-2 over leads RT4-1 (L4) to the line circuit via leads T4 and R4. This transmission path is extended through the winding of transformer 3T to leads T4-1 and R4-1 to the PBX facility. The transmission path of the 1st station is also extended via transformer 3T over leads T1 and R1 of cable 411 to FIG. 5, add-on transfer connecting circuit 501 for the 1st link-1st (transfer) line. Since relay 5AO in that circuit is unoperated at this time the subscriber may communicate only with the PBX line subscriber. In order to communicate with the intercom connected station the 1st station subscriber must first place the PBX subscriber on hold and then operate the pickup key associated with line L5.

Note that the station to which the 1st station is not communicating is maintained on hold in the manner previously described. When the 1st station is communicating with the PBX facility transmission is possible over the audio leads in the manner previously described and over the video leads in the following manner.

Turning to FIG. 4, transmission from camera C1-1 is extended over video output leads VOT1 and VOR1 and cable 203 to FIG. 3 and via the video switch 304 and video output leads VOT-1 and VOR-1 to the PBX facility. Transmission from the PBX facility is via video input leads VIT-1, VIR-1, video switch 304, leads VIT1 and VIR1 over cable 203 to FIG. 4 to the 1st video set 401 and to screen S1-1 therein.

When it is desired to establish an add-on transfer connection such that a three-party conference is established between the 1st station, the 27th station via the 1st link of the intercom and the PBX facility, the party at the 1st station enables the add-on transfer key

thereat such as key 3ADD-ON, shown in FIG. 3. At each station capable of handling add-on transfer calls there is an add-on key for each line circuit which may be added to the intercom link. Thus in our example key 3ADD-ON is assumed to be associated with line circuit 302 (line 4). The enabling of the 3ADD-ON key operates in much the same manner as the enabling of the register recall key keeping in mind that it is again necessary to establish which of the links the calling 1st station 301 is currently associated with. The circuitry to accomplish this function may be seen beginning on FIG. 7. Current from the base emitter junction of transistor 7Q1 from add-on transfer control 701, which add-on transfer control is uniquely associated with the 1st link, is extended via resistor 7R6 over the AOC lead of cable 511.

Digressing momentarily, it will be noted that as shown in FIG. 7 there is one add-on transfer control circuit for each of the links. Accordingly, add-on transfer control circuit 702 is associated with the 2d link while add-on transfer control circuit 703 is associated with the 3d link. Each of these add-on transfer control circuits provides current via its respective AOC lead to cable 511 in the manner previously described. However, as will be detailed, only one of these leads is cut through to the signaling station, that lead corresponding to the link to which the calling subscriber is connected.

Continuing in FIG. 7, the current on lead AOC from the 1st link add-on transfer control circuit is extended via cable 511 to the matrix network 1st link, FIG. 23, via the vertical multiple AOC to the enabled 24F-3 contact shown in FIG. 24 associated with the 1st matrix. Associated with that vertical multiple the 24F relays of the 1st matrix and 27th matrix is operated corresponding to the 1st station communicating with the 27th station. Thus the current on lead AOC is extended from vertical multiple AOC to the associated horizontal multiples AO-1 and AO-27 (not shown). However, since only one of the add-on transfer keys is operated at this point only the current from the associated matrix will be effective.

Accordingly, continuing in FIG. 24, current from the horizontal multiple AO-1 and cable 411 is extended to FIG. 3 and through the operated 3ADD-ON key and over lead AOL(4)-1 and cable 411 to FIG. 5 via forward-biased diode 5CR1 and resistor 5R1 to the base of transistor 5Q1 in all add-on transfer connecting circuits such as 501, 601, 602 associated with the 1st station-1st (transfer) line. At this point the 5AO relay in each of the add-on transfer connecting circuits such as 501, 601, 602 will try to operate. Only one 5AO relay can operate however since the 5AO relays are also controlled by the associated add-on transfer control circuits. This will now be described.

Continuing now in FIG. 7, current flowing through transistor 7Q1 turns on that transistor thereby turning on transistor 7Q2 causing negative potential to be extended via released break contact 7Z-4 to one side of the 7Z relay winding. Relay 7W, however, has negative potential connected to one side of its winding via released break contact 7W-1. The other side of the 7W relay winding at this time is connected to ground via resistor 7R1. Accordingly, the 7W relay operates and locks operated to negative potential on lead MXH back

on cable 511 to FIG. 25 and hence through enabled make contact 26LB-2 to battery. The 7W relay and the 7Z relay are connected in a typical WZ relay fashion such that when current stops flowing through the emitter base junction of transistor 7Q1 (for example upon release of the depressed add-on key 3ADD-ON, FIG. 3) transistor 7Q1 turns off turning off transistor 7Q2 thereby removing the shunt path from relay 7Z and allowing relay 7Z to operate at that time.

When relay 7W first operates ground is supplied via enabled make contact 7W-3 and released break contact 7Z-3 over lead WO to all of the add-on transfer connecting circuits associated with the 1st link. At this time ground is also extended over lead LO to all of the add-on transfer connecting circuits associated with the 1st link. Thus, as shown in FIG. 5 ground via lead WO is extended through released break contact 5AO-1 to the 5AO relay in the add-on transfer connecting circuit 501 1st link-1st (transfer) line. Ground is also extended to the 5AO relays (not shown) in all of the other 1st link add-on transfer connecting circuits. However, since only the 1st (transfer) line add-on key at the 1st station is operated only the 5AO relay associated with the 1st link-1st (transfer) line add-on transfer connecting circuit 501 can operate at this time. The ground on lead LO supplies a holding path for operated relay 5AO.

Continuing now in FIG. 5, the operation of relay 5AO connects negative potential to lead AOLP-1 via enabled make contact 5AO-5 to light the AO lamp at the station. Also the tip and ring leads T1 and R1 which have been extended from the line circuit 302 are connected via enabled make contacts 5AO-3 and 5AO-4 to the associated add-on transfer control circuit 701, FIG. 7, and through the control circuit via transformer 7T1 and capacitor 7C1 over leads TC and RC of cable 511 to the vertical multiple 1st link, FIG. 23. Accordingly, audio communication is possible from the PBX line to the vertical multiple of the 1st link. Since both the calling and called stations have their respective audio paths connected to the 1st link via their respectively operated matrix relays, all three stations are connected together for audio communication. Thus at this point audio transmission is possible between all of the parties to the conference without regard to which of the pickup keys, 3PU4 or 3PU5, are operated at the 1st station.

It should be noted at this point that although three-way audio transmission has been enabled video transmission is still only possible between two stations at a time, that is, between the 1st station and the 27th station via the intercom link or via the 1st station and the PBX line via the line circuit 302. The video portion of the transmission thus continues to be responsive to the operation of the respective pickup keys for line L5 (the intercom) and line L4 (the PBX transfer line). The control of this separation of audio and video functions will now be described.

Turning to the matrix network, FIG. 24, it will be noted that associated with vertical multiple TD in each of the links there is a 24R1 resistor to ground. When a station is connected to a link in the wideband mode its respective 24V relay is operated and resistance ground is thereupon connected to the TD vertical multiple. Accordingly, when the 1st station is connected to the link

the 1st matrix relay 24V is operated thereby connecting ground via resistor 24R1 and enabled make contact 24V-1 to vertical multiple TD. Since the 27th matrix is also operated at this time the respective 24R1 resistor (not shown) in the 27th matrix 2301 is also connected to vertical multiple TD. Thus these resistors are in parallel. This parallel combination of resistors is extended via lead TD and cable 2710 to FIG. 26 to the winding of the 26TD relay therein. The 26TD relay is connected to the null point of a conventional bridge with the resistors just described forming one leg. The bridge is unbalanced when two vertical multiple relays operate thus supplying a parallel combination of resistors over lead TD. Thus relay 26TD does operate. When only one such matrix relay is operated the bridge is balanced and the 26TD relay remains normal.

Accordingly, since two matrix relays are now operated the 26TD relay operates. As shown in FIG. 27, ground is provided via enabled make contact 26TD-1 and enabled make contact 26TD1-2 over lead TRI. It should be remembered that the 26TD1 relay is always operated on all calls after the particular link circuit has been selected. Thus, ground is extended over lead TRI and cable 511 back to the add-on transfer connecting circuit for the 1st link-1st (transfer) line, FIG. 5, and via forward-biased diode 5CR2 and released break contact 5TR-3 and zener diode 5CR5 to the base of transistor 5Q2. Ground on this lead prevents the operation of transistor 5Q2 at this time.

Since the 5AO relay has been operated negative potential via enabled make contact 5AO-2 is present via resistors 5R4 and 5R5 on capacitor 5C1. Capacitor 5C1 will not charge sufficiently at this point to turn on the 5Q2 transistor since the charge will not be high enough to break down zener diode 5CR5. Relay 5AO also provides negative potential via enabled make contact 5AO-2, forward-biased diode 5CR4, released break contact 5LCT-6 and the LKC1 lead of cable 511 to the line circuit FIG. 27 and via released break contact 27TRB-3 and lead LKC, FIG. 26 and cable 2710 to the vertical multiple associated with the 1st link, FIG. 23, and back through the enabled 24A relay contacts associated with each enabled matrix over the corresponding horizontal multiple leads LK- to each of the stations connected to the 1st link.

Turning now to FIG. 17, negative potential on lead LK is supplied via forward-biased diode 17CR6 to maintain the station circuit operated regardless of the status of the pickup keys thereat. Thus a party at the 1st station may depress the PBX line circuit 3PU4 key thereby communicating directly to the PBX line and the station circuit associated with the intercom link will be maintained operated from battery provided over lead LK from the add-on transfer circuit in the manner just described. So long as this condition exists either of the two parties connected to the intercom may view the PBX line by depressing the associated PBX line. The video path from the PBX station to the viewing line is not via the multilink intercom but rather by direct access because of the fact that the PBX line key is depressed. If both intercom parties operate their respective PBX line keys video switch 304 in line circuit 302 is arranged, as detailed in the aforementioned Bush-Crouse-Saltus application, to prevent interference between stations.

In the situation where the intercom parties are viewing each other via the intercom link, the PBX party receives a blank screen. The circuitry which prevents the transfer of video transmission into the intercom 5 from the PBX line may be seen from the add-on transfer circuit, FIG. 5. This follows because ground is present either on the TR1 lead from the link circuit as previously described or from lead VSG, cable 305, from the PBX line circuit, FIG. 3, if the PBX line is enabled.

2.11 Transfer of PBX Line to The Intercom

In the situation where one of the intercom parties hangs up the PBX connection will be extended through the add-on transfer connecting circuit 501 to the 1st link previously serving that station. Let us assume that the original calling station 301 goes on-hook. Accordingly, as shown in FIG. 3, the grounds associated 20 with the A5-1 lead of line L5 and with the A4-1 lead of line L4 are removed. The video switch 304 in the PBX line then releases and ground is removed from lead VSG.

When the calling 1st station goes on-hook, as 25 discussed above, ground is removed from the A5-1 lead of the station circuit shown in FIG. 15, thus, transistor 16Q4 turns off. However, as shown on FIG. 17, negative potential has been extended from the matrix over lead LK to hold operated relays 17A and 30 17B. However diode 17CR2 prevents this negative potential from holding transistor 16Q2 in FIG. 16 on. Thus, since transistor 16Q4 turns off when the station goes on-hook the ground is removed from the V lead thereby releasing the video relay 24V in the matrix associated with the now on-hook station.

Turning to FIG. 26, it will be recalled that the TD lead from the winding of relay 26TD monitored the condition of the various matrices such that when only one matrix relay, 24V, is operated the 26TD relay releases. Thus, when the 24V relay of the on-hook station goes normal the bridge becomes balanced and the 26TD relay releases. As shown in FIG. 27, ground is removed from the TRI lead via now released make contact 26TD-1 and enabled make contact 26TD1-2. The TRI lead is extended via cable 511 to the add-on transfer connecting circuit, FIG. 5, to diode 5CR2. Since at this point grounds have been removed from leads VSG and TRI, capacitor 5C1 is free to charge sufficiently to turn on transistor 5Q2. When transistor 5Q2 turns on ground is extended to one side of the winding of the 5TR relay. This ground is also extended at this time via released break contact 5LCT-5 and forward-biased diode 5CR8 over lead TRB and cable 511 to the link circuit, FIG. 27, to operate relay 27TRB. Relay 27TRB operating removes the battery potential from lead LKC, FIG. 26, via now enabled break contact 27TRB-3.

It will be recalled that this potential had been extended through the matrix circuit to the LK leads of all station circuits. Thus, when battery is removed from the LK lead the 17A and 17B relays in those station circuits associated with stations at which the intercom pickup key is not operated release. As shown in FIG. 7, relay 7W remains operated at this point from battery on lead MXH from the 1st link circuit, FIG. 25. Thus since the 1st link circuit remains enabled while at least

one station remains on the associated link the add-on transfer circuit previously enabled remains enabled and ground continues to be supplied on lead LO to FIG. 5 to hold operated relay 5AO.

Turning now to FIG. 5, in the add-on transfer connecting circuit 501 ground has been extended to one side of the 5TR relay winding. The other side of the winding is extended via lead TR and cable 511 to FIG. 27 in the link circuit. Since relay 27TRB is operated battery is extended via enabled make contact 27TRB-1 to the TR lead. Thus, as shown in FIG. 5, relay 5TR operates thereby operating relay 5LCT from ground via enabled make contact 5TR-4. Accordingly, the battery which has been extended via lead LKC1 from the add-on transfer connecting circuit is now removed via enabled break contact 5LCT-6. At this time battery is extended via enabled make contact 5LCT-6 to hold relay 5TR operated.

Continuing now in FIG. 5, ground is extended via enabled make contact 5TR-4 over lead PA and cable 305 to the line circuit 302 over lead PA. Ground on this lead serves to enable the video switch 305 in the line circuit 302 such that transmission is possible from the PBX quad over leads VOT, VOR, VIT, VIR and cable 305 to the add-on transfer connecting circuit, FIG. 5, and via now enabled make contacts 5LCT-3, 5LCT-4, 5LCT-1, and 5LCT-2 to leads VOTC, BORC, VITC, and VIRC of cable 511 to FIG. 23 and the respective vertical multiples of the wideband quad of the 1st link. Transmission from this quad is then extended via the operated 24V relay contacts associated with the still enabled 27th matrix back to the video set of the 27th station, FIG. 2. Accordingly, the 27th station is now in wideband communication as well as in audio communication via the intercom link with the PBX station even though the 27th intercom station had not initiated a call to the PBX line. This action is automatic when the other party to a previously established multilink intercom connection goes on-hook.

At this point it should be noted that the 17RV relay in the station circuit associated with the 27th station, as detailed with respect to the 1st station in FIG. 15, 16, and 17, is normal since the 27th station had been a called station. In the event the 27th station had been a calling station, the 17RV relay in the associated station circuit would be operated as a reversing relay in the manner previously described. However, for PBX calls the convention has been adopted that the wideband quad lead comes into the intercom in the reversed manner so consequently it is unnecessary to reverse the quad at the intercom system. Accordingly, in the event that the called intercom party had gone on-hook it would be necessary to insure that the 17RV relay goes normal in the associated calling station. This can be seen from FIG. 17 where it will be recalled that the battery potential has been removed from the LK lead upon initiation of the transfer feature thereby removing operate potential from the 17RV relay winding in the calling station. Thus, communication for audio and wideband is possible from either party previously connected to one of the links of the intercom system to a PBX line established through the transfer circuit whenever the other party to the intercom connection has released.

2.12 Conclusion

While the equipment of this invention has been shown in a particular embodiment wherein a group of key telephone stations have been arranged for video connection between two selected stations on any one of a number of links of a multilink intercom system, it is understood that such an embodiment is intended only to be illustrative of the present invention and numerous other arrangements may be devised by those skilled in the art without departing from the spirit and scope of the invention.

For example, some or all of the key stations could be replaced by computer terminals arranged to supply information to any of the other stations or computers over any one of the links. Under these conditions the intercom connection could be initiated either from one of the key telephone stations or from one of the computers to any number of other computers.

What is claimed is:

1. In a key telephone system wherein connections are established between any one of a number of stations and any one of a number of lines in response to the enabling of a key associated with a selected one of said lines at an enabling one of said stations and wherein one of said lines is arranged for intercommunication between said stations, the combination comprising

a plurality of intercom links each accessible by any of said stations, each link having first and second busses and each station having first and second pairs of communication leads connectable to said busses,

a plurality of link control circuits each uniquely associated with one of said intercom links and each adapted for controlling said associated intercom link,

a register circuit common to all of said stations and to all of said link control circuits,

means in each of said link control circuits for communicating the availability of said associated link for the establishment of connections thereon,

means in said register circuit jointly operative in response to the enabling of the intercommunication line key at a calling one of said stations and to a communicated connection availability of one of said links for receiving first signals from said calling station,

means in said register responsive to the receipt of said first signals for establishing a connection from said calling station to said available link in a first manner from a first pair of communication leads of said station to said first bus of said available link and from a second pair of communication leads of said station to said second bus of said available link, and

means in said register responsive to the receipt of other signals transmitted from said calling station to said register for establishing a connection from said available link to a called one of said stations in a second manner from said first pair of communication leads of said called station to said second bus of said available link and from said second pair of communication leads of said called station to said first bus of said available link.

2. The invention set forth in claim 1 further comprising

a plurality of station circuits each associated with one of said stations and interposed between said associated station and said register circuit and wherein

said first signals are communicated to said register circuit directly from said station circuit associated with said calling station, and

said other signals are communicated to said register circuit from said calling station over said first manner connection to said link.

3. The invention set forth in claim 2 wherein each said link further includes a third bus and each said station includes a third pair of communication leads connectable to said third bus of each said link, and wherein said first manner connection includes a connection from said third pair of leads from said calling station to said third bus of said available link and a connection from said third pair of leads from said called station to said third bus of said available link.

4. The invention set forth in claim 3 wherein said register circuit is further responsive to additional signals communicated thereto for establishing a connection from said third bus of said available link to said third pair of communication leads from a second called station while inhibiting a connection to said available link from said first and second pairs of communication leads from said second called station.

5. The invention set forth in claim 4 wherein said first pair and said second pair of communication leads from each said station comprise a wideband quad, one of said pair arranged for wideband transmission from said station and the other of said pair arranged for wideband receiving at said station, and wherein said third pair of communication leads from each said station is arranged for audio transmission.

6. The invention set forth in claim 5 wherein said additional signals are communicated to said register circuit over said audio pair connection to said link from said calling or said called station.

7. The invention set forth in claim 5 wherein said additional signals are communicated to said register circuit directly from said station circuit associated with said second called station in response to signals communicated to said station circuit from said calling or first called station.

8. The invention set forth in claim 3 further comprising

hold control means associated with each of said stations and operative in response to hold signals transmitted from said associated station for inhibiting the audio and wideband connections to the link while maintaining the link operated for subsequent reconnections thereto.

9. The invention set forth in claim 3 further comprising

transfer control means for controlling connections established between said calling and called stations on any of said links and between said calling and called stations and a line other than said intercommunication line,

said transfer control means comprising

means for establishing a connection from said third pair of communication leads associated with said other line to said third bus of said available link irrespective of the operational status of the line key associated with said other line at either said calling or called stations, and

means responsive to the enabling of said other line key at said calling station for establishing a connection between said first and second pairs of communication leads associated with said other line and said first and second pairs of communication leads from said calling station while inhibiting said first manner connection to said available link.

10. The invention set forth in claim 9 wherein said transfer control circuit further comprises

means operative in response to the on-hook condition of either said calling or called station for connecting said first and second pairs of communication leads of said other line to said available link so that said other line and said station remaining connected to said link may communicate over said link in audio and bidirectional wideband fashion.

11. The invention set forth in claim 2 wherein each of said link control circuits further comprises

means for communicating the unavailability of said associated link for establishing connections thereto, and

means for communicating the busy condition of said associated link,

said register circuit further comprising

means concurrently operative with the enabling of said first signals receiving means for enabling said busy condition communicating means in said link control circuit associated with said communicated available link, and

means operative in response to said receipt of said other signals for disassociating said register from said link control circuit associated with said communicated available link and for enabling said unavailability communicating means in said link control circuit.

12. The invention set forth in claim 11 further comprising

means controlled jointly by said register circuit and said link control circuits for enabling said available communicating means exclusively in one of said link control circuits,

means in each of said link control circuits for maintaining the associated link control circuit unavailability communicating means enabled while any station remains connected to said associated link, and

means for inhibiting the enabling of any link control circuit availability communicating means while said busy communicating means of any other link control circuit is enabled.

13. The invention set forth in claim 12 wherein certain stations have associated therewith a plurality of special feature keys,

means controlled jointly by said register circuit and by said link control circuits and operative in response to the enabling of a first one of said keys at a station connected to one of said links for reassociating said register with said link control circuit associated with said one link while said unavailability communicating means in said link control circuit is enabled.

14. The invention set forth in claim 13 further comprising

means for inhibiting said reassociating means while said busy condition communicating means in any of said link control circuits is enabled.

15. In combination

- a plurality of communication stations, each station arranged for two-way transmission over an audio path, outgoing wideband transmission over a transmit path and incoming wideband transmission over a receive path;
- a plurality of intercom links common to all of said stations, each of said links comprising an audio bus, a wideband transmit bus and a wideband receive bus;
- a plurality of link control circuits each individually associated with one of said links, each said link control circuit operative for controlling connections to said associated link;
- a register circuit common to all of said stations and accessible from said stations over a first path and over an audio path;
- means controlled by signals transmitted to said register from a calling station over said first path for seizing a link control circuit associated with an idle one of said links;
- means operative in response to said seized link control circuit for establishing an audio connection from said audio path of said calling station to said register through said idle link;
- means responsive to first signals transmitted over said audio path from said calling station for establishing first manner wideband connections to said wideband transmit bus of said idle link from said transmit path of said calling station and from said wideband receive bus of said idle link from said receive path of said calling station;
- means responsive to other signals transmitted over said audio path from said calling station for establishing an audio connection from said audio bus of said idle link to said audio path of a called station; and
- means controlled by said first manner wideband connection means for establishing second manner wideband connections from said transmit path of said called station to said wideband receive bus of said idle link and from said receive path of said called station to said wideband transmit bus of said idle link.
16. The invention set forth in claim 15 further comprising
- means in said link control circuits for signaling the busy, available and unavailable status of each of said links,
- means operative in response to said seizing of said link control circuit associated with said idle link for enabling said busy signaling means of said seized link control circuit, and
- means operative in response to an audio connection to said called station from said seized link for inhibiting said enabled busy signaling means and for enabling said unavailable signaling means of said seized link control circuit associated with said seized link.
17. The invention set forth in claim 16 further comprising
- means concurrently operative with said busy signaling inhibiting means for exclusively enabling the availability signaling means of one of said other link control circuits associated with an other idle link.

18. The invention set forth in claim 17 wherein said seizing means is controlled by said exclusively enabled availability signaling means of said link control circuits.
19. The invention set forth in claim 15 wherein said register further comprises
- means operative in response to a connection to said called station from said seized link control circuit for transferring control of said control circuit to said station connected to said link associated with said control circuit, and
- means concurrently operative with said transferring means for releasing said register from said seized link control circuit and for preventing a reseizure of said link control circuit from another calling station while said link control circuit is controlled by any said connected station.
20. The invention set forth in claim 19 further comprising
- means for accessing said register from certain of said stations over a third path,
- means controlled by signals transmitted to said register over said third path from a station connected to one of said links for reseizing said link control circuit associated with said link to which said third path signaling station is connected,
- means responsive to further signals transmitted to said register from said third path signaling station for establishing an audio connection from said reseized link to a second called station, and
- means controlled by the previous establishment of a second manner connection to said reseized link for inhibiting a concurrent second manner connection from said reseized link to said second called station.
21. The invention set forth in claim 20 wherein said third path includes a connection from said reseized link control circuit, said link connected to said third path signaling station, a key associated with said third path signaling station and a connection from said key to said register.
22. The invention set forth in claim 21 wherein said third path further includes said audio connection from said third path signaling station.
23. The invention set forth in claim 20 wherein said third path includes a connection from said reseized link control circuit, said link connected to said third path signaling station, a key associated with said third path signaling station, and a connection from said key to said second called station.
24. The invention set forth in claim 15 further comprising a station circuit interposed between each said station and said register, said station circuit comprising
- means operative when said station circuit is associated with a calling station and controlled by said first manner wideband connection means for reversing said wideband receive path and said wideband transmit path from said calling station so as to effect said first manner connection, and
- means operative when said station circuit is associated with a called station and controlled by said second manner wideband connection means for inhibiting said reversing means so as to effect said second manner connection.
25. The invention set forth in claim 24 wherein said station circuit further comprises

means operative when said station circuit is associated with a second called station and controlled by said wideband connection means for inhibiting a wideband connection to said link from said second called station.

26. In a key telephone system having a plurality of stations arranged for both audio and wideband transmission, each station connectable to incoming lines for both audio and wideband transmission and each station station to other stations for both audio and wideband transmission, the combination comprising

at least two intercom links common to said stations, means for determining which of said links are idle, transfer control means, first means for establishing audio transmission simultaneously to at least one line and a plurality of stations connected to said one line through said

5

15

transfer control means and a determined idle one of said links,

second means including said transfer control means for establishing wideband transmission between said line and only one of said stations through said determined idle link, and means responsive to a disconnection of said one station from said determined idle link for establishing wideband transmission between said line and another one of said stations connected to said link.

27. The invention set forth in claim 26 further comprising means interposed in said wideband transmission path for ensuring the bidirectional integrity of said wideband transmission regardless of the order in which said stations are connected to said link.

UNITED STATES PATENT OFFICE
CERTIFICATE OF CORRECTION

Patent No. 3,705,269

Dated December 5, 1972

Inventor(s) John Pringle Audesirk, Charles Ernest Morse and
Gordon Douglas Weed

It is certified that error appears in the above-identified patent
and that said Letters Patent are hereby corrected as shown below:

Column 43, line 10, at the beginning of the line, change
"station" to --connectable--.

Signed and sealed this 4th day of June 1974.
